[57] ABSTRACT

Improved electrophotographic printing systems are provided in accordance with the teachings of the present invention wherein a plurality of coded data

records containing document information are scanned by code sensing devices and presented to electrophotographic imaging means at which the document information is imaged upon a photosensitive member and processed according to electrophotographic techniques for subsequent presentation to a transfer station. Code information from each of the plurality of data records scanned as provided by the code sensing devices is processed in accordance with selected conditions for printing and print and skip information is generated in sequence therefrom. The sequence of print and skip information is propagated through logic circuitry at a rate corresponding to the rate at which document information from each of the plurality of coded data records is electrophotographically processed in such manner that each bit of information in the print and skip information sequence is present at a predetermined output of the logic circuitry at a time when document information from the data record associated therewith is presented to the transfer station. At the transfer station, a transfer member which is normally maintained in a position displaced from the photosensitive member is continuously charged by an ion charging device and a transfer member assembly is provided to selectively bring the transfer member from its displaced position into a transfer relationship with the photosensitive member in response to the presence of a bit representing a print signal at the predetermined output of the logic circuitry.

ELECTROPHOTOGRAPHIC PRINTING SYSTEMS

BACKGROUND OF THE INVENTION

This invention relates to electrophotographic printing techniques and more particularly to selective electrophotographic printing systems wherein desired conditions for printing may be set and document information present on a plurality of coded records may be selectively printed whenever the coded conditions of any such plurality of coded records meets the desired conditions set.

The widespread adoption of data processing techniques to all facets of business and commerce has rendered the storage of business records, mailing lists, employee files and the like on coded data records commonplace. Although the information stored in this form may be selectively retrieved by the utilization of data processing equipment, it is often desirable to directly provide the information present on the coded records retrieved in the conventional form of permanent documents which may be directly employed without further duplication. Where the coded data records take the form of a data card or the like which contains both a data area for coding and an information area wherein document information is contained in a form viewable by an observer but not readable by the data processing equipment, it was often necessary to first employ the data processing equipment for the purposes of selective retrieval and thereafter to utilize conventional copying equipment to duplicate the document information from each data card retrieved so that permanent documents which could be directly employed were obtained. As this multi-step mode of selective information retrieval was often time consuming, required the maintenance of costly specialized equipment which was frequently not utilized to its full potential and often failed to provide the information retrieved in a document format most suitable for utilization; the need became manifest for selective printing equipments capable of receiving coded data records in this format and directly printing the document information contained on any of such coded data records meeting the selection conditions set while providing a wide range of selectively.

For instance, although similar problems obtain wherever business records, personnel files or any other material which is to be selectively printed is stored on coded records of the foregoing kind, the need for selective printing equipment of the type mentioned above may be readily appreciated by a consideration of the specific case of mailing lists from which labels for addressing envelopes are prepared. In a typical case, addressing information for each individual present in a mailing list is maintained in document form on a codable data record or card and such data record or card is coded with information designating certain characteristics, i.e. business data, personal data, interest data personal and business, and the like, of the individual whose address is present on that record. These data records may be maintained in separate groups in accordance with preselected characteristics or may be individually retrieved in accordance with the characteristics selected for particular mailing by known data processing techniques assuming that the cost of the necessary data processing equipment therefor is justified by the frequency of its utilization. Thereafter, the data records selected may be loaded in bulk in elec-

trophotographic printing apparatus which acts to retrieve information in bulk, such as the label printing apparatus disclosed in U.S. Pat. No. 3,674,352 issued July 4, 1972, to Raymond A. Wilmes and assigned to the Xerox Corporation. In the electrophotographic printing apparatus disclosed, a plurality of data cards in the form of address cards, microfiche or the like are loaded and processed on a continuous basis so that document information from each of the data cards loaded is sequentially reproduced on a paper web. Upon the completion of the run of selected data cards, the paper web may be removed from the electrophotographic printing apparatus and cut or torn along perforated portions of the web to obtain the desired label for addressing purposes from each of the data cards loaded. The electrophotographic printing apparatus disclosed in U.S. Pat. No. 3,674,352, supra, employs highly efficient continuous electrophotographic processing techniques wherein a photosensitive member in the form of a drum is relied upon and charging, exposure, development, transfer and cleaning stations are disposed about the periphery thereof so that continuous processing is achieved. Thus, as each of the plurality of data cards is fed toward the exposure station, a peripheral portion of the photosensitive member, whose area is sufficient to accommodate the document information on the data card, is sensitized at a charging station formed by conventional corotron apparatus and exposed to image radiation representing the document information on the data card so that a latent electrostatic image is formed. Thereafter as the peripheral portion of the photosensitive member containing the latent electrostatic image formed rotates at a constant angular velocity toward the development station, a latent electrostatic image of the document information on the next data card is in the process of being formed on an adjacent peripheral portion of the photosensitive member. As each peripheral portion of the photosensitive member containing a latent electrostatic image rotates through the development station, conventional cascade development techniques are employed to cascade triboelectrically charged toner particles over the photosensitive member so that charged toner particles are deposited in a selective pattern on each peripheral image portion of the photosensitive member in accordance with the charge pattern exhibited by the latent electrostatic image formed. Upon the completion of rotation through the development station, each peripheral image portion of the photosensitive member rotates toward the transfer station wherein the toner image is transferred to a paper web or sheet. At the transfer station, corona charging techniques are employed to insure that high quality toner image transfer to the paper web or strip results while problems associated with the charging inefficiency, humidity sensitivity and susceptibility to toner clogging upon a breakage of the transfer web inherent in other charging apparatus, such as transfer rollers, are avoided. In this apparatus, it should be noted, that corona charging techniques may be employed without difficulty because as each image formed on the photosensitive member is transferred, the transfer member may be continuously maintained in contact with the photosensitive member and hence problems associated with bringing a charged transfer member in

contact with a photosensitive member are avoided. Upon completion of the image transfer, the toner image present on the paper web is fused to render it permanent while the peripheral portion of the photosensitive member which has been processed through the transfer station rotates to a conventional cleaning station where the residual toner is removed so that such peripheral portion of the photosensitive member may again be employed in the formation of another latent electrostatic image when the rotation of the photosensitive drum next brings it into an operative relation with the charging and exposure stations associated with the latent electrostatic image formation to thereby achieve continuous electrographic processing.

Although the prior art, as exemplified by the DICK STRIP printing apparatus disclosed in U.S. Pat. No. 2,859,673 to I.M. Hix et al., has provided some highly specialized equipments which appear capable of providing successful selective printing operations for specified input and output conditions; such prior art has not, to the knowledge of the inventors herein, provided a generalized approach to selective electrophotographic printing systems which enable the high speed, high quality selective printing of document information present on coded data records taking any conventional format while allowing a relatively wide ambit of selectively with respect to the form of coding employed to be maintained. More particularly, the prior art selective printing apparatus of which the present inventors are aware has only provided highly specialized selective printing apparatus which has been unable to produce high quality toner images on a transfer member because highly efficient corona charging transfer techniques were considered unavailable due to problems associated with air gap ionization when a charged transfer member is selectively brought into contact with a toner image to be transferred. To avoid these problems lower efficiency charging techniques were employed which resulted in relatively low quality toner image formation on the transfer member as well as relatively long transfer intervals. Furthermore, the charging techniques employed tended to be highly susceptible to changing humidity conditions and whenever misfeed or breakage of the transfer member would occur, for instance in the case of a transfer roller, would directly act to remove toner from the photosensitive member and subsequently become clogged with toner. In addition, selection information generally was physically rotated with the photosensitive member so that only limited data processing functions were available and hence the selectivity associated with a given printing operation was highly restricted and only a limited number of control functions could be derived from the selection information which was processed.

Therefore, it is an object of the present invention to provide electrophotographic printing systems which enable high speed selective printing of document information present on coded data records which may take any conventional format.

It is a further object of the present invention to provide selective electrophotographic printing systems employing ion charging techniques at the transfer station thereof so that high quality toner images of document information which is selectively printed may be produced on a transfer member.

It is an additional object of the present invention to provide selective electrophotographic printing systems wherein a wide ambit of selectivity is available to an operator and may readily be increased or decreased to suit a specific need.

It is another object of the present invention to provide selective electrophotographic printing systems wherein selection information is logically processed independently of document information but propagated in a manner which relates in time to the processing of such document information whereby such logically processed selection information may be employed to control various operations in the processing of such document information.

It is a further object of the present invention to provide selective electrophotographic printing systems wherein document information from each of a plurality of coded data records is processed using continuous electrophotographic imaging techniques but only document information from selected ones of said coded data records is selectively transferred to a transfer member using improved transfer station charging and transfer member handling techniques.

Other objects and advantages of the present invention will become clear from the following detailed description of an exemplary embodiment thereof, and the novel features will be particularly pointed out in conjunction with the claims appended hereto.

In accordance with the teachings of the present invention, an electrophotographic printing system is provided wherein a plurality of coded data records containing document information are scanned by code sensing means and presented to electrophotographic imaging means whereat the document information therefrom is imaged upon a photosensitive member and processed according to electrophotographic techniques for subsequent presentation to a transfer station; code information from each of said plurality of data records scanned as provided by said sensing means is processed in accordance with selected conditions for selective printing and print and skip information is generated in sequence therefrom; said sequence of print and skip information is propagated through logic circuit means at a rate corresponding to the rate at which document information from each of said plurality of coded data records is electrophotographically processed in such manner that each bit of information in said print and skip information sequence is present at a predetermined output of said logic circuit means at a time when document information from the data record associated therewith is presented to said transfer station; at said transfer station, a transfer member which is normally maintained in a position displaced from said photosensitive member is continuously charged with ion charging means and means are provided to selectively bring said transfer member from said displaced position into a transfer relationship with said photosensitive member in response to the presence of a bit representing a print signal at said predetermined output of said logic circuit means.

The invention will be more clearly understood by reference to the following detailed description of an exemplary embodiment thereof in conjunction with the accompanying drawings in which:

FIG. 1 illustrates selective printing apparatus and associated components of an exemplary embodiment of a

selective electrophotographic printing system in accordance with the teachings of the present invention;

FIGS. 2A-2D depict exemplary timing apparatus for the instant embodiment of the selective electrophotographic printing system;

FIG. 3 illustrates an exemplary embodiment of a scanning and selection circuit for the instant embodiment of the selective electrophotographic printing system;

FIG. 4 shows an exemplary embodiment of a logic and control circuit which may be employed in the instant embodiment of the selective electrophotographic printing system;

FIG. 5 is a detailed pictorial view of a portion of the selective transfer member mechanism illustrated in FIG. 1; and

FIGS. 6A-6D illustrate the various relationships which obtain between the transfer member and the toner image to be transferred during a typical selective transfer operation in the embodiment of this invention shown in FIG. 1 wherein FIG. 6A depicts the relationship between the transfer member and the toner image at a point where selective transfer is initiated, FIG. 6B shows this relationship at a point where the selective transfer member has been brought into a transfer relationship with the toner image to be transferred, FIG. 6C depicts this relationship at a point when the transfer of the toner image from the photosensitive member to the transfer member has just been completed and FIG. 6D shows this relationship at a point where the transfer member is displaced from the photosensitive member at the completion of a selective transfer.

Referring now to the drawings and more particularly to FIG. 1 thereof, there is depicted a selective printing apparatus which constitutes that portion of the exemplary embodiment of the instant invention that employs electrophotographic concepts originally disclosed in U.S. Pat. No. 2,297,691, issued to C.F. Carlson on Oct. 6, 1942. Such selective printing apparatus is comprised of a continuously rotating photosensitive drum 20, having displaced along its periphery a charging station G, an exposure station C, a development station D, a transfer station E, and a cleaning station F.

Photosensitive drum 20 has been illustrated as a simple two layer drum including an insulating member 31 and conductive member 32. As the photosensitive drum 20 forms no part of the instant invention per se, it is here sufficient for an appropriate understanding of this disclosure to appreciate that if the selective printing apparatus is employed in conjunction with conventional electrophotographic techniques, the conductive member 32 may be formed of any suitable conductive material or a nonconductor overcoated with a conductive foil. Similarly, the insulating member 31 may be formed of a material displaying photoconductive characteristics such that the insulating member 31 is normally insulating and exhibits excellent charge retentivity but may be rendered selectively conductive by the application of electromagnetic radiation thereto through a light and dark pattern representing an object to be copied or, alternatively, reflection exposure techniques may be employed. The materials relied upon in the formation of the insulating member 31 may be selected from any of the well-known group of materials conventionally employed in the electrophotographic processes.

Charging station G may take the conventional form of one or more charging devices which act in the well-known manner to sensitize the photosensitive drum 20 by charging the surface of the insulating member 31 to a uniform potential. For example, charging station G may comprise a charging device of the type described in U.S. Pat. No. 2,588,699, issued to C.F. Carlson on Mar. 11, 1952, or as described in U.S. Pat. Nos. 2,836,725 and 2,879,395, to Vyverberg and Walkup, respectively.

Exposure station C disposed about the periphery of the photosensitive drum 20 takes the conventional form of a projection system 33 wherein optical transmission techniques are relied upon to sequentially image a light and dark pattern representing each data card 1 of a deck of data cards onto the surface of the insulating member 31. In FIG. 1, a slit exposure device 34 has been generally indicated, however, any optical system which relies upon lenses or the like may be readily employed. Additionally, although the exposure station C, illustrated in FIG. 1, has been shown positioned in such manner that the rotating photosensitive drum 20 is initially sensitized by the charging station G and subsequently exposed at station C, it will be apparent that the processing steps of charging and exposure may be carried out simultaneously by altering the position of the exposure station C and/or the charging station G. Furthermore, although only the simplified processing steps of a single charging operation and a single exposure are depicted in FIG. 1, it will be obvious that additional electrophotographic processing steps such as another charging operation may be employed in the formation of the latent electrostatic image or the latent electrostatic image formed may be reversed or otherwise altered by the use of such additional processing steps as is well known to those of ordinary skill in the art.

Development station D comprises hopper arrangement 35 suitable for subjecting incremental portions of the photosensitive drum 20 to a cascade development step or the like as is well known to those of ordinary skill in the art. For example, the hopper arrangement 35 driven by a developer motor 24 may take any of the conventional forms of devices generally employed in electrophotographic development equipment to flow charged, finely divided particles, known as toner, to the imaged area to deposit in a selective pattern of the electrostatic image previously formed.

Image transfer station E comprises a charging means 30 for imposing a predetermined charge on a portion of a transfer strip 9 within close proximity to the photosensitive drum 20 to thereby effect transfer of a toner image from the surface of the photosensitive drum 20 to the transfer strip 9 upon the latter engaging the former. The transfer strip 9 may be formed of suitable transfer material such as paper, plastic or any of the other well-known materials conventionally employed as transfer materials. The charging means such as those discussed in conjunction with the charging station G may be employed, it being appreciated that any charging means capable of imposing a predetermined charge level on the surface of the transfer strip 9 may be employed at the image transfer station E. The charging means 30 illustrated in FIG. 1 may be connected to a suitable source of potential, for example a conventional d.c. supply.

Cleaning station F may take the conventional form of rotating fur brush cleaning means, wiper means or cascade cleaning means which act in a well-known manner to remove residual toner from the surface of the photosensitive drum 20. As each of these techniques is well known to those of ordinary skill in the art, it is here sufficient to simply state that the cleaning station F acts to remove residual toner particles from the surface of the photosensitive drum 20 to thereby place the same condition for reuse.

A description of the remaining component parts of the selective printing apparatus depicted in FIG. 1, and in part in FIG. 2, is hereinafter set forth in conjunction with a general summary of the operation of such apparatus.

A plurality of data cards various ones of which are to be selectively printed are stacked in a feeder tray 2 and are fed, one by one, by means of a feeder roller 6 through a scanning station B and a projection system 33 to a restack tray 49. Coaxially mounted about a drive shaft 5 of feeder roller 6 are two laterally displaced collars 10 and 10'. Each of the collars 10 and 10' includes an adjustment screw 19 or 19' for enabling lateral and rotational adjustment along and about the drive shaft 5. Further, collars 10 and 10' have coaxially attached thereto timing discs 4 and 4', respectively. Coaxially mounted on collar 10 is a collar 11, and on collar 10' a collar 11'. Collars 11 and 11' include adjustment screws 21 and 21', respectively, for lateral and rotational adjustment along and about the collars 10 and 10', respectively. Coaxially attached to the collars 11 and 11' are, respectively, timing discs 3 and 3'. Fixedly positioned between the disc combinations defined by discs 3 and 4, and 3' and 4', is a light source 7. On the side of the disc combination 3 and 4 remote from light source 7 is a photosensitive device 8, while on the side of disc combination 3' and 4' remote from light source 7 is a photosensitive device 8'. Upon each revolution of the feeder roller 6 in the clockwise direction, the open angular slot θ as depicted in FIG. 2B will permit light radiation to pass between the light source 7 and the photosensitive device 8. Further, upon each such revolution of the feeder roller 6, the open angular slot θ' as depicted in FIG. 2C will permit light radiation to pass between the light source 7 and the photosensitive device 8'. The photosensitive device 8 constitutes a portion of a system clock 70 of the logic and control circuit depicted in FIG. 4. As hereinafter described in detail with respect to the operation of such circuit, photosensitive device 8 generates for each revolution of the feeder roller 6 a dark edge triggering pulse the duration of which is determined by the preset displacement between the leading edge of disc 3 and the trailing edge of disc 4 ($360 - \theta$) as the feeder roller 6 is rotated in the clockwise direction. The photosensitive device 8' constitutes a portion of a selective transfer timing generator means 98 (also hereinafter described with respect to FIG. 4) which produces a clock pulse having a duration indicated by the interval ($360 - \theta'$) defined by the leading edge of disc 3' and the trailing edge of disc 4' for each clockwise revolution of the feeder roller 6. Since the relative positions of discs 3 and 4, and 3' and 4', are such that angle θ is less than angle θ' , and since the leading edge of disc 3 leads the leading edge of disc 3' by the angle ϕ as in-

dicated in FIG. 2D, it will be apparent that the pulses provided by photosensitive device 8 will be synchronized with the pulses provided by photosensitive device 8', but will be of lesser duration and lead the pulses provided by photosensitive device 8' by the time required for the disc 6 to rotate through an angle of ϕ degrees. Accordingly, as hereinafter described with respect to the logic and control circuit depicted in FIG. 4, since a single revolution clutch 15, when energized, is responsive to the leading edge of the system clock 70, while the selective transfer means 25 is immediately activated thereafter by the pulse provided by the selective transfer timing generator means 98, the transfer strip 9 is brought to the speed of the photosensitive drum 20 prior to or to the strip engaging the toner image on the photosensitive drum 20 at transfer station E.

Scanning station B is located along the path of travel of the data cards 1 from the feeder tray 2 to the restack tray 49, at a position before the slit exposure device 34 of the projection system 33. It is from this station B that the scanning and selection circuit of FIG. 3 scans pre-coded information on the data cards 1 for providing to the logic and control circuit of FIG. 4 print and skip signals in a properly timed sequence representing the actual rate at which data cards are scanned at station B. It is noted that each such signal is a print signal only if the selection of particular preconditions as established in the scanning and selection circuit of FIG. 3 by the state of the selection modules therein, are satisfied by the pre-coded information scanned from the data card to which such signal relates by the determination of the presence of particular pre-coded information thereon and, when established, the absence of other particular pre-coded information thereon. Further, though such signal is derived almost simultaneously with the scanning of the data card to which it relates at scanning position B, and appears at the output of inverter and buffer stage 69 depicted in FIG. 3, it is utilized in a timed sequenced manner by the logic and control circuit of FIG. 4 for various coordinated control functions of the various elements of the selective printing apparatus of FIG. 1. More specifically, such circuit of FIG. 4 is adapted to receive and sequentially shift such signals in their timed sequence through a plurality of stages so that there is acquired a direct correspondence between the stage to which a particular signal has been shifted, and the position to which the image on the photosensitive drum 20 to which such signal pertains has been rotated. Thus, the type of signal (print or skip) at a particular stage may be utilized by logic circuitry connected to such stage to control functions desired at the corresponding position of the associated image.

To achieve the above-noted operations, there are provided a card edge detector 50 that generates a pulse upon the leading edge of each data card 1 coming into the detecting station B, and a plurality of scanning means 50-50C at the scanning station B which are so positioned as to sense pre-coded information on each data card as it reaches station B. It is noted in this regard that the data cards, for the purpose of this exemplary embodiment, are characterized by a physical format that includes a row of identical bit locations, aligned perpendicularly to the direction of card travel, for pre-coding such cards in accordance with a

predetermined code as applied to the visible document information of such data cards. Thus, by selective marking particular bit locations in a well-known manner, pre-coded information is made available for scanning at the scanning station B as the bit locations of a data card pass immediately adjacent to the plurality of scanning means 50-50C. Further, to achieve scanning at scanning station B by means of scanning means 50A-50C only during that interval of time that the bit locations of the data card entering the scanning station B are immediately adjacent to the scanning means 50A-50C, the scanning and selection circuit of FIG. 3 as hereinafter described, utilizes the aforesaid pulse from edge detector 50 to provide a periodic scanning function delayed by that increment of time that it takes each data card to move from the position whereat its edge was detected to the position whereat the bit locations on such data card are immediately adjacent the scanning means 50A-50C.

Various alternative card formats as to bit locations, and selective rearrangements of the space relationship of the scanning means 50A-50C, will be apparent to those of ordinary skill in the art. Further, it will be apparent to those of ordinary skill in the art that if the scanning and selection circuit of FIG. 3 is modified so as to achieve sequential scanning by a single scanning means, rather than simultaneous scanning by a plurality of scanning means 50A-50C, an appropriate data card format for the bit locations may include a column of bit locations aligned in the direction of the data card travel and provided with a clock track or external clocking means.

The sequential passage of data cards from the scanning station B through the projection system 33 to the restack tray 49 will cause optical images of the document information on each of the data cards passing through the slit exposure device 34, to be sequentially projected, by means of mirror and lens arrangements of the projection system 33, upon the surface of said photosensitive drum 20. Since the photosensitive drum 20 is continuously driven at a constant angular velocity such that the surface thereof is moving at a velocity equal to that of the data cards moving past the exposure devices 34, latent electrostatic images of the document information of the data cards are formed on successive incremental areas of the photosensitive drum 20 as they pass through the exposure station C. Further, as any data card scanned at scanning station B will require an increment of time to pass from station B to the slit exposure device 34, and since the various stations about the periphery of the photosensitive drum 20 are at fixed spatial positions, and the photosensitive drum 20 has a constant angular velocity, the aforementioned print or skip signal for each data card scanned precedes in time, and has a particular time relationship between, the formation of the latent electrostatic image associated with such data card, and the subsequent operational steps affecting such incremental area upon which such image has been formed as such area is moved through the various peripheral stations D, E, F and G.

Accordingly, as described in detail hereinafter with respect to the logic and control circuit of FIG. 4, print or skip signals for the data cards scanned may be utilized by such circuit to provide a plurality of logic and

control functions, so as to achieve optimized coordinated control operations at the development station D and the image transfer station E. Further, as disclosed in U.S. Pat. Application No. 221,193 filed concurrently with this application and assigned to the same assignee, such print or skip signals may be utilized by a novel fuser arrangement to achieve additional operational benefits. Since such fuser arrangement is not a necessary component of the present invention, but, rather, a preferred form of a fuser arrangement that may be utilized with the exemplary embodiment of this invention if toner fixing is desired, only a general reference thereto is made herein.

Difficulties inherent to selective printers that form latent electrostatic images for each data card scanned but only transfer developed images on a selective basis, are background-toner buildup and excessive use of toner at the development stations. Background-toner build-up in any such printer often occurs because the latent electrostatic images sequentially formed on the rotating photosensitive drum are all sequentially developed at the development station, and then only selective ones of such developed images are transferred at the image transfer station. Thus, the cleaning stations in any such printer is required not only to remove residual toner from those incremental areas from which toner has been transferred at the image transfer station but, also, all the toner from the incremental areas from which no toner has been removed at the prior image transfer station because of a skip condition for such incremental area. Since all cleaning stations are less than ideally efficient in their removal of all toner from the incremental areas passing therethrough, background-toner will increase cumulatively for those incremental areas that may be successively skipped a number of rotations of the photosensitive drum.

To minimize the unnecessary use of toner, as well as background-toner buildup, the aforesaid print or skip signal for each data card scanned is utilized, as hereinafter described, by the logic and control circuit of FIG. 4, to energize the developer motor 24 just prior to the entry in the development station D of an incremental area having thereon a latent electrostatic image of a data card having a print signal associated therewith, and to maintain such developer motor 24 energized only so long as any such incremental area so identifiable with a print signal is within the chamber of the development station D. Thus, the hopper arrangement 35 will be operated in an intermittent manner to decrease the number of latent electrostatic images developed at station D whose toner is not to be subsequently transferred at the image transfer station E because of skip signals associated therewith. Since such intermittent operation of the hopper arrangement 35 assures development of the least all the latent electrostatic images to be subsequently transferred at the image transfer station E, as well as providing a decrease in the unnecessarily developed images, the amount of toner expended is decreased while the background-toner buildup is minimized, resulting in higher quality printing at decreased cost.

To achieve selective image transfer at station E in accordance with the aforesaid print or skip signals provided to the logic and control circuit of FIG. 4, the selective printing apparatus depicted in FIG. 1 may

comprise a selective transfer mechanism, a strip drive mechanism and a strip restraining mechanism. The selective transfer mechanism 25 is preferably of a kind disclosed in U.S. Pat. Application No. 221,230 filed concurrently with this application and assigned to the same assignee and, as depicted in FIG. 1 and partially in FIG. 5 hereof, comprises a pair of parallel extending T shaped support members 25a, the horizontal portions of each of which is coupled at one end thereof to an anchor member 25b in a manner to permit pivotal movement about a fixed axis 25c which is parallel to the axis of rotation of photosensitive drum 20; a support shaft 25d extending between the central portions of T support members 25a and having a longitudinal axis which is parallel to axis of rotation of the photosensitive drum 20; a strip turn-around roller 25e concentrically positioned about support shaft 25d and freely rotatable about their common longitudinal axis; a stripper bar 25f extending between the ends of the horizontal portions of the T support members 25a furthest removed from the anchor members 25b, and extending in a direction parallel to the axis of rotation of the photosensitive drum 20; a base member 25g upon which the vertical portions of T support members 25a are supported and fixedly attached; and a bistable drive 25h having one end thereof attached to the base member 25g and the other end thereof fixedly positioned, such bistable drive including a normally energized contraction solenoid 27 for maintaining the selective transfer mechanism 25 (more particularly, the strip turn-around roller 25e) at a position removed from the surface of the photosensitive drum 20, and an expansion spring 28 for pivotably impelling at a high velocity, the selective transfer mechanism 25 in an arched upward direction toward the photosensitive drum 20 upon the deenergization of the solenoid 27. The strip drive mechanism in the instant exemplary embodiment takes the form of a single revolution clutch 15, a strip advance pin wheel 16 the intermittent rotation of which is controlled by the clutch 15, and a strip alignment roller 17; while the strip restraining device takes the form of a friction drag 18. Clutch 15 is of a type that rotates a fixed predetermined amount upon each activation thereof by the leading edge of a pulse derived from the system clock 70. Accordingly, upon each activation of the clutch 15, the strip advance pin wheel 16 is rotated a fixed amount which in turn cause the transfer strip 9 to move a fixed amount, during a single machine cycle of, for example, 332 milliseconds. Preferably, the lateral movement increment of transfer strip 9 for each machine cycle is made equal to the size of the developed image to be transferred, thus acquiring the economies associated with adjacent image printing on the transfer strip 9.

As depicted in FIG. 1, the strip 9 is threaded in such a manner as to pass from a strip supply 13, through the friction drag 18, around the turn-around roller 25e, under the stripper bar 25f, through a fuser 40 if toner fixing is desired, around the strip alignment roller 17, and about the pin wheel 16, and into a strip receiving tray 14. This arrangement normally maintains the strip 9 in a constant state of relatively high tension (for example 8 oz.), whether the transfer strip 9 is moving preparatory to or during selective transfer of the developed image at the image transfer stage E, or sta-

tionary during a skip condition; and whether the transfer strip 9 is moving toward or away from the photosensitive member 20 preparatory to or completion of, selective transfer.

Briefly, the operation of selective transfer mechanism 25 of FIG. 1 may be readily appreciated from a perusal of the print cycle diagrams of FIGS. 6A-6D. As previously noted, the logic and control circuit of FIG. 4 includes a plurality of stages to which print or skip signals are sequentially shifted in direct correspondence to the particularly spatial positions of the corresponding images on the photosensitive drum 20. At the time a developed image having associated therewith a print signal arrives at the position slightly prior to that indicated in FIG. 6A, the associated print signal has been shifted to a particular one of such plurality of stages which has connected thereto logic circuitry that (i) causes the single revolution clutch 15 to initiate clockwise rotation of the strip advance pin wheel 16 so as to promptly accelerate the velocity of the strip 9 to the surface velocity of the photosensitive drum 20; and (ii) after a short delay, to release a selective transfer relay 26 so as to deenergize the contraction solenoid 27. Upon such deenergization, the expansion spring 28 causes the T support members 25a to pivot upwardly and, in so doing, to cause the strip turn-around roller 25e and the stripper bar 25f to also move upwardly, the latter by a greater distance in view of its greater relative position from the pivot axis 25c. FIG. 6B indicates the event status at that time when the contraction solenoid 27 has fully released and allowed maximum contact between transfer strip 9 and photosensitive drum 20.

As the turn-around roller 25e is on the side of the photosensitive drum 20 closest to the pivot axis 25c, and the stripper bar 25f is on the other side of such drum and thus closer to the strip alignment roller 17, the above-noted upward pivotal movement causes the strip 9 to engage the photosensitive drum 20 in an arc of contact because an adjustable spring stop 28a on rod 28b within the expansion spring 28 is adapted to permit a total upward stroke that carries the turn-around roller 25e to a position that though removed from surface of the photosensitive member 20, causes the taut transfer strip 9 to move beyond a tangential relationship with the photosensitive member 20. In cooperation with the adjustable spring stop 28a, is an adjustable solenoid stop 27a that limits the downward movement of an armature 27b of the solenoid 27. By means of spring stop 28a and solenoid stop 27a the terminal positions of movement of the turn-around roller 25e may be clearly established and, if necessary, finely adjusted so as to acquire a controlled constant arc of contact whenever the transfer strip 9 is engaged with the photosensitive member 20 during a print mode, and to maintain the transfer strip 9 at a specific position in close proximity of the surface of the photosensitive member 20 during a skip mode. The total lack of engagement between the turn-around roller 25e and the surface of the photosensitive drum 20 under all conditions of operations enables high velocity movements of such roller toward the photosensitive drum 20 without fear of damage thereto. Since the transfer strip 9 is maintained in a condition of high tension and is brought from a disengaged position to a position of en-

gagement with the photosensitive drum 20 in a very short interval of time (for example, a distance of $\frac{1}{6}$ of an inch in 30 ms) a constant arc of contact is achieved almost immediately upon deenergization of solenoid 27.

FIG. 6B illustrates the relative position of developed image to be printed and the engagement of the moving strip 9 with the surface of the photosensitive drum 20 in an arc of contact. In the exemplary case wherein the toner images are approximately 1 inch in length, such arc of contact may have a length of approximately 3/10 of an inch. Since the toner transfer is practically instantaneous upon engagement of the transfer strip 9 and the photosensitive member 20, the transfer of toner for those incremental areas within the initially established arc of contact is practically instantaneous. Notwithstanding that the charging means 30 may preferably be constantly energized, air gap ionization is avoided by the short time interval engagement and disengagement of the transfer strip 9 and the photosensitive member 20 during selective printing operations, as well as the positioning of the charging means 30 so that its effective radiation pattern does not include the entrance point of the aforesaid arc of contact. This is considered in detail in the aforesaid U. S. Pat. Application Ser. No. 221,230.

FIGS. 6C and 6D illustrate the conditions that pertain as the image being transferred moves through and away from the image transfer station E. As will be apparent from FIG. 6C, the further transfer of the developed image after the initial engagement of the strip 9 and the photosensitive drum 20 to form an arc of contact will be at the velocity of such drum and strip, since it is at this velocity that subsequent incremental areas of transfer strip 9 come into the arc of contact and then result in instantaneous toner transfer. FIG. 6C illustrates the conditions that pertain when the trailing edge of a toner image to be transferred is fully within the arc of contact between the transfer strip 9 and photosensitive drum 20; where, therefor if the next following toner image is not to be transferred, transfer strip 9 must be removed from the photosensitive drum 20 to avoid transferring any part of the next toner image. FIG. 6D shows the status of events which pertain when the single revolution clutch 15 has moved one complete toner image increment and, thus, itself comes to a stop and thus stops the longitudinal motion of the transfer strip 9 while photosensitive drum 20 continues to rotate. As hereinafter described with reference to the logic and control circuit of FIG. 4, the contraction solenoid 27 will be energized and the strip 9 returned to its normal disengaged position if the stage of such circuit preceding the stage referred to above with respect to FIG. 6A, has not received a print signal indicating that the following image on the photosensitive drum is also to be printed. With respect to the transition from the conditions that prevail as indicated in FIG. 6C and those that prevail in FIG. 6D, the energization of solenoid 27 will cause, in the exemplary case of 1 inch toner images the stripper bar 25f to move down and into engagement with transfer strip 9 in the vicinity of the beginning of the transferred image which usually does not include significant toner and thus does not result in a smear problem. Such movement of the stripper 25f in conjunction with the downward move-

ment of the turn-around roller 25e causes forces to be applied at two closely positioned locations on opposite sides of the transfer station E to overcome the electrostatic and other forces of attraction between the transfer strip 9 and the photosensitive member 20. In those situations wherein toner smear may be a significant problem, an alternative for the stripper bar 25f would be the substitution therefor of a vacuum bar extending in close proximity to the surface of the transfer strip 9 opposite to the surface upon which toner images are formed and activated during all non-print modes of operation.

An exemplary embodiment of the scanning and selection circuitry for association with the selective printing apparatus of the embodiment of this invention shown in FIG. 1 is schematically illustrated in FIG. 3 while an exemplary embodiment of the appropriate logic and control circuitry for association with such apparatus is depicted in FIG. 4. In the description of FIGS. 3 and 4 which follows, it has been assumed that conventional, commercially available TTL logic is utilized throughout for each of the gates, inverters, registers and flip-flops employed, while conventional integrated circuit operational amplifiers are relied upon for the amplifiers shown. Therefore, as will be apparent to those of ordinary skill in the art, complementary logic such as NOR elements are often relied upon to accomplish AND and/or OR functions so that design requirements can be optimized both in terms of a reliance upon logic elements which are readily available in the market place as well as the utilization of a minimum number of components. Accordingly, it will be appreciated by those of ordinary skill in the art that any of the specific logic components or arrangements described in conjunction with FIGS. 3 and 4 may be replaced by other components or groups thereof which produce similar output conditions in response to similar input conditions even though the mode of logical operation employed thereby differs at the component level from that set forth in conjunction with FIGS. 3 and 4 so long as the resulting modification is calculated to achieve the same result or a slightly varied result directed to the same purpose. Furthermore, although TTL logic and integrated circuit operational amplifiers, as mentioned above, are assumed to be utilized throughout the exemplary circuitry embodiments described in conjunction with FIGS. 3 and 4, MSI, individual circuit components or MOS implemented circuit chips may be readily substituted without any deviation from the inventive teachings contained herein.

Scanning and Selection Circuit

Referring now to FIG. 3, there is shown a schematic representation of an exemplary scanning and selection circuit for the embodiment of the selective printing apparatus illustrated in FIG. 1. The exemplary scanning and selection circuit depicted in FIG. 3 comprises the card edge detector 50, the plurality of scanning means 50A-50C, a plurality of data channels A-C associated therewith, a plurality of print selection modules 1-3, a decoder means formed by gating means 51 and 52, and gated output means 53. In a consistent manner with the description of the exemplary embodiment of the selective printing apparatus set forth above, it has been as-

sumed that the raw data input which contains the document information to be selectively printed takes the form of individual data cards containing, in addition to visible document information, a row of 12 bit locations which are selectively encoded by marking or not marking each such bit location in accordance with a predetermined code applied to the document information contained in a given deck of such data cards. Additionally, it has been assumed that selection is achieved by scanning the mark or no mark information contained in a selected three of such 12 bit locations; however, as will be apparent to those of ordinary skill in the art from the symmetry of the exemplary circuit depicted in FIG. 3, any number of bit locations may be simultaneously scanned, depending upon the degree of selectivity required, by merely relying upon more or fewer scanning means 50A-50C associated with data channels A-C, or physically repositioning one or more of such scanning means over a different bit location. Accordingly, even though three scanning means 50A-50C and three data channels A-C are illustrated in FIG. 3, it will be appreciated by those of ordinary skill in the art that this showing is intended by way of illustration and not by way of limitation.

The document detector 50 and each of the plurality of data scanning means 50A-50C may take the form of individual photosensitive devices such as phototransistors, photodiodes or the like, physically positioned, as indicated in FIG. 1, at appropriate locations to detect the information sought to be obtained. The card edge detector 50 is positioned, as shown in FIG. 1, to detect the leading edge of each data card as it is fed from the feeder tray 2 toward the scanning station B, due to the radiation blockage achieved by the card edge. As the document detector 50 only acts to ascertain the presence of an edge of a data card, capacitive or mechanical detectors could be employed in place of the photosensitive device illustrated. Similarly, each of the plurality of data scanning means 50A-50C are positioned opposite the bit positions which are desired to be scanned when a data card is in the predetermined scanning position, station B, and produces a signal representative of the mark or no mark condition of the bit location being sensed due to the differential in the radiation level received by the photosensitive device when mark and no mark conditions are detected. Suitable preamplification stages, such as conventional transistor amplifiers or operational amplifiers, are included within the card edge detector 50 and each of the data scanning means 50A-50C so that the signals produced thereby, negatively directed pulses representing mark information in the case of phototransistors, are suitably amplified to selected logic levels prior to their application to the remaining circuit portions depicted in FIG. 3. Additionally suitable noise traps, such as d.c. shunts to ground, are also preferably provided to reduce noise and avoid spurious output signals.

The output of the card edge detector 50 is connected to the scanning window timing generator means 54 which acts in response to the receipt of each input pulse from the card edge detector 50 to generate a pulse having a sufficient duration, such as 25 milliseconds, for scanning and data utilization to take place after a delay interval, such as 120 milliseconds,

equal to the time interval necessary for a data card or the like whose leading edge has been detected by the card edge detector 50 to reach an appropriate scanning location beneath the plurality of data scanning means 50A-50C. Although the scanning window timing generator means 54 may conveniently take the form of a conventional monostable multivibrator having a duty cycle equal to the desired pulse duration, 25 milliseconds for the case stated above, which is arranged in a manner well-known to those of ordinary skill in the art, to be triggered through a conventional delay device which in this case would exhibit a delay interval equal to 120 milliseconds; it is preferred that the design of the scanning window timing generator means 54 insure against spurious outputs due to the detection of the trailing edge of the data card. This can be conveniently achieved by gating the triggering pulses for said monostable multivibrator through another monostable multivibrator whose duty cycle is equal to the desired delay and which thereby produces a pulse of proper duration whose trailing edge acts to trigger the monostable multivibrator having a duty cycle of 25 milliseconds. The output of the scanning window timing generator means 54 is connected through conductor 55 to the flip-flop 56, to a timing input relied upon in the circuitry indicated in FIG. 4, as indicated, and to each of the data channels A-C, where as shall be seen below, it acts to open and close the scanning window in an appropriately timed manner so that only data is scanned and utilized. The time during which the scanning window is opened, as aforesaid, is preferably made sufficiently long so that data is read even under conditions where the data card or mark information thereon is skewed within acceptable limits. The flip-flop 56 may take the form of a conventional monostable multivibrator arranged to be triggered by the trailing edge of the pulse provided by the scanning window timing generator means 54 and has a duty cycle, sufficient to produce a pulse of appropriate duration such as 1½ milliseconds, to apply a gating signal for the gated output means 53. The output of the flip-flop 56 is connected to a timing input of the gated output means 53 and also applied to the conductor 55 to extend the time the scanning window of data channels A-C is open by 1½ milliseconds. Although a monostable flip-flop 56 has been illustrated, it will be apparent to those of ordinary skill in the art that alternative gating arrangements may be employed to achieve the same result.

The output of each of the plurality of scanning means 50A-50C are each connected to their associated data channels A-C, respectively. As the data channels A-C are identical, only data channel A has been shown in detail while the corresponding structure of data channels B and C has been indicated in FIG. 3 by the appropriately annotated blocks. Data channel A, as shown in FIG. 3, comprises threshold amplifier means 57, inverter means 58, flip-flop 59 and an inverter and buffer stage indicated by block 60. All of the elements illustrated within data channel A, as indicated by the dashed block, may comprise conventional integrated circuit operational amplifiers and standard TTL components commercially available from semiconductor manufacturers such as Texas Instruments Corporation or Fairchild Electronics. The threshold amplifier means 57 is connected at the inverting input thereof to the

output of scanning means 50A while the threshold level thereof is set at the input thereof connected to potentiometer 61. The threshold amplifier means 57 acts in the well-known manner to discriminate between negative going input pulses exceeding the threshold setting thereof and those which do not exceed such threshold so that only negatively directed pulses exceeding a predetermined level are inverted and applied to the output thereof. The threshold setting of the threshold amplifier means 57 is set to a level to insure that only negatively directed pulses representing true mark information reach the output thereof and in this manner provides noise isolation. Additional isolation from spurious inputs may be provided by a.c. coupling and noise suppression networks of the type well-known to those of ordinary skill in the art. Accordingly, a positively directed pulse at the output of the threshold amplifier means 57 is indicative that mark information is present, while the absence of a pulse at the output of the threshold amplifier means 57 is indicative that no mark information is present and hence if a bit location is being scanned at this time that no mark is present. The output of the threshold amplifier means 57 is connected to the input of the inverter means 58 which may take the form of a conventional TTL inverter. The output of the inverter means 58 is connected to the input of the flip-flop 59. The flip-flop 59 is conventional; however, the clear input thereof is connected to the output of the inverter means 58 while the preset input thereof is connected to receive timing pulses from the scanning window timing generator means 54 through conductor 55. Due to these connections, as well known to those of ordinary skill in the art, the flip-flop 59 will normally be held in a reset condition and hence may not be set by a negatively directed pulse from the inverter means 58 unless a timing pulse is present on conductor 55. Similarly, when the timing pulse on conductor 55 terminates, the flip-flop 59 will be returned to a reset condition and held in this state until the next timing pulse occurs regardless of the presence of spurious inputs from the inverter means 58. If the timing associated with the operation of the scanning window timing generator means 54 is recalled, it will be appreciated that the flip-flop 59 effectively acts as a scanning window whereby mark or no mark information may be stored therein only when the scanning window timing generator means 54 indicates that a data card is in a position for scanning by the production of a suitable timing pulse. The output of the flip-flop 59, wherein a positive or high level represents mark information while ground or a low level represents a no mark condition, is connected to the inverter and buffer stage 60. The inverter and buffer stage 60 may take the form of a conventional TTL inverter which exhibits a low output impedance and inverts the output levels of the flip-flop 59 applied thereto so that at the output thereof a low level represents mark information and a high level represents no mark information in the bit locations sensed while the low impedance output insures against noise on the line. Although a plurality of signal inversions are employed in each of data channels A-C, it will be appreciated that this is merely a function of the logic arrangement employed and could be readily avoided by the utilization of other components and/or logic arrangements, such as deriving a low mark output level from the flip-flop 59.

The output of each of data channels A-C is connected from the inverter and buffer stage 60 therein to each of the selection modules 1-3 in the manner indicated in FIG. 3. As the AND selection modules 1 and 2 are in all ways identical while OR selection module 3 varies from the AND selection modules 1 and 2 only by the substitution of a NAND gate for the single NOR gate employed therein and a slightly different data off condition, only the AND selection module 1 has been illustrated in detail in FIG. 3 while AND selection module 2 and the OR selection module 3 have been schematically indicated by the annotated blocks in FIG. 3. Therefore, although only AND selection module 1 is described in detail below, it will be appreciated that selection modules 2 and 3 take the same form and perform the same function except in areas specifically mentioned below.

The AND selection module 1 comprises a three positions switch means S_{1A} , S_{1B} and S_{1C} associated with each data channel A-C, respectively, a NOR gate 61 and a mode selection switch S_{M1} . Each of the three position switch means S_{1A} , S_{1B} and S_{1C} may take the form of the mechanical switch means shown and is employed to select whether mark or no mark information is to be detected from the data channel A-C associated therewith or alternatively a don't care condition may be selected by placing the switch means in the OFF position. The top position contact of each of the three position switch means S_{1A} , S_{1B} and S_{1C} , annotated MARK, is employed when it is desired to select data cards having marks in the corresponding bit position scanned and is connected directly to the output of the inverter buffer stage 60 of the data channels A-C associated therewith in the manner indicated in FIG. 3. Thus, when a mark condition is scanned, a low level output will be present at the mark position contacts of each of the three position switch means S_{1A} - S_{1C} while the detection of a no mark condition will be indicated by a high level output. The center position contact of each of the three position switch means S_{1A} , S_{1B} and S_{1C} , annotated OFF, is utilized when the mark or no mark condition of the particular bit position being scanned is unimportant to the selection sequence being carried out. The off position contact of each of the three position switch means S_{1A} , S_{1B} and S_{1C} is connected to ground G through a conductor and hence this contact is maintained in a low condition regardless of the mark or no mark condition scanned. The bottom position contact of each of the three position switch means S_{1A} , S_{1B} and S_{1C} , annotated NO MARK, is employed when it is desired to select a condition where the bit position being scanned does not contain a mark. This contact of each of the three position switch means S_{1A} , S_{1B} and S_{1C} is connected through an inverting gate 63A-63C, which may take the same form as the inverting gate 58, to the output of its associated data channel A-C. Thus, in the case of the NO MARK terminal of the three position Switch means S_{1A} - S_{1C} , a mark condition will be indicated by a high level output while the selected no mark condition is indicated by a low level output condition. Accordingly, it will be seen that at each of the three position switch means S_{1A} - S_{1C} , whenever the condition selected is present in the bit position of the data card being scanned, a low level output will be applied from the selected position contact of the three position switch means S_{1A} - S_{1C} to the wiper con-

tact thereof; however, when a non-selected condition is detected a high level output will be applied to the wiper contact from the selected contact.

The wiper contacts of each of the three position switch means S_{1A} - S_{1C} are each connected through conductors 64A - 64C, respectively, to the NOR gate 61. The NOR gate 61 may take the form of a conventional TTL NOR gate; however, due to the input conditions employed, the NOR gate 61 functions in the same manner as an inverting AND gate. Thus, whenever all the inputs from the plurality of the three position switch means S_{1A} - S_{1C} are low, indicating that the selected input conditions are satisfied by the bit positions of the data card being scanned, the AND input conditions for NOR gate 61 are satisfied and the output thereof goes high. However, when one or more of the inputs from the plurality of the three position switch means S_{1A} - S_{1C} are high, indicating that the selected input conditions have not been satisfied by the bit positions of the data card being scanned, the AND input conditions for NOR gate 61 are not satisfied and the output thereof goes low. At this point in the description of FIG. 3, it will be appreciated that additional bit position selectivity is readily available and may be achieved merely by adding further data scanners 50D-Z, the data channels D-Z therefor as well as their associated inverter gates 63D - 63Z, three position switch means S_{1D} - S_{1Z} and inputs 64D - 64Z to NOR gate 61.

The output of NOR gate 61 is connected through conductor 65 to terminals a and d of the mode selection switch S_{M1} . The mode selection switch S_{M1} may take the form of a conventional double pole three position switch, such as a wafer switch or the like, wherein the wiper contacts are ganged as indicated for concurrent rotation. The upper and lower contacts a and d of the mode selection switch S_{M1} are connected to the output of NOR gate 61, as aforesaid, while the central pair of contacts b and c are grounded as indicated in FIG. 3. The mode selection switch S_{M1} is employed so that the mode of operation of the selective printing apparatus with respect to data cards meeting the AND data requirements set by the three position switch means S_{1A} - S_{1C} may be selected. More particularly, the mode selection switch S_{M1} may be employed to cause the printing, i.e., select, of the document information contained on data cards meeting the AND data requirements set by the three position switch means S_{1A} - S_{1C} by setting the mode selection switch S_{M1} to the SELECT position wherein contacts a and b are utilized; to cause the document information contained on data cards meeting the AND data requirements set by the three position switch means S_{1A} - S_{1C} not to be printed, i.e., a skip, by setting the mode selection switch S_{M1} to the SKIP position wherein contacts c and d are employed; and to disable the action of the AND selection module 1 by setting the mode selection switch S_{M1} to the OFF position, wherein contacts b and c are employed, whereby any data conditions which may have been set by the three position switch means S_{1A} - S_{1C} do not affect the printing or non-printing of the document information on a defined data card.

The upper wiper contact of the mode selection switch S_{M1} is connected to the conductor annotated SELECT 1 indicating that the logic level on this conductor is associated with select or print information

from the AND selection module 1, while the lower wiper contact thereof is connected to the conductor annotated SKIP 1, indicating that the logic level on this conductor is associated with skip or no print information. The manner is which the logic levels on the SELECT 1-3 and SKIP 1-3 conductors are utilized to control the operation of the selective printing apparatus according to the present invention will be explained below. Here, however, it is sufficient to appreciate that whenever the AND data conditions set by the three position switch means S_{1A} - S_{1C} are present on a data card being scanned, a high level will be present at the output of NOR gate 61 while when such data conditions are not present a low level output will be present at the output of NOR gate 61. Thus, when the mode selection switch S_{M1} is in the SELECT position, contacts a and b, conductor SKIP 1 will always have a low level thereon due to the grounded condition of contact b while conductor SELECT 1 may have a high or low logic level thereon depending upon whether or not the data card being scanned meets the AND data conditions set by the three position switch means S_{1A} - S_{1C} . Conversely, when the mode selection switch S_{M1} is in the SKIP position, contacts c and d, conductor SELECT 1 will always have a low level thereon due to the grounded condition of contact c while conductor SKIP 1 may have a high or low logic level thereon depending upon whether or not the data card being scanned meets the AND data conditions set by the three position switch means S_{1A} - S_{1C} . In the OFF position of the mode selection switch S_{M1} , both the SELECT 1 and SKIP 1 conductors are in a low logic condition due to the grounded condition of contacts b and c. Therefore, it will be seen that the AND selection module 1 allows for the selection of data cards coded via marks or no marks having all of up to three specified bit location criteria while the mode selection switch S_{M1} allows the operator to define data cards so selected to be either selected for printing or skip mode operation.

The AND selection module 2 is identical, as aforesaid, to the AND selection module 1 and therefore allows for a second selection of data cards coded via marks or no marks having all of a second set of up to three specified bit location criteria while its mode selection switch S_{M2} (not shown) allows the operator to define the second set of data cards so selected to be either selected for printing or skip mode operation. The OR selection module 3 differs from the AND selection module 1, described above, in that the OFF position of each of the three position switch means S_{3A} - S_{3C} is tied to a high level rather than ground and a NAND gate is substituted for the NOR gate 61 wherein all of the connections to such NAND gate are the same as those specified in conjunction with NOR gate 61. The substituted NAND gate, as will be appreciated by those of ordinary skill in the art, acts as an inverting OR gate rather than an inverting AND gate and hence the substituted NAND gate will provide a high output level whenever any one of the specified bit conditions set on the three position switch means S_{3A} - S_{3C} (not shown) is present while providing a low level output only when none of such specified data card bit conditions are present. The OFF position of each of the three position switch means S_{3A} - S_{3C} is here tied to a high level so that

a select will not occur whenever a don't care condition is specified in the absence of at least one of the specified criteria. Thus, the OR selection module 3 allows for a third selection of data cards coded via marks or no marks having any one of a third set of up to three specified bit location criteria while its mode selection switch S_{M3} (not shown) allows the operator to define the third set of data cards so selected to be either selected for print or skipped. Although three selection modules 1-3 have been shown in FIG. 3, it will be apparent to those of ordinary skill in the art that a greater or lesser number of selection modules may be employed to provide the necessary selectivity for a desired application by merely adding or subtracting AND and/or OR selection modules to the cascaded selection modules depicted in FIG. 3.

The select conductors SELECT 1-3 of each of the selection modules 1-3 are connected to one of the logic inputs of NOR gate 51 while each of the skip conductors SKIP 1-3 are connected to one of the logic inputs of NOR gate 52. Additionally, another input to NOR gate 51 is connected to ground while the output of NOR gate 51 is connected to an input of NOR gate 52. The NOR gates 51 and 52 may take the same form as NOR gate 61; however, the input conditions of NOR gates 51 and 52 are such that NOR gate 51 is operated as an inverting OR gate while NOR gate 52 is operated as an inverting AND gate. The NOR gates 51 and 52 form a decoder circuit for the various select and skip logic inputs provided by the selection modules 1-3 which function in such manner that a skip input has priority so that document information from a scanned data card which produces a skip output from one of the selection modules 1-3 and also produces a select output from another of the selection modules 1-3 will not be printed. The NOR gate 51 functions as an inverting OR gate, as aforesaid, and accordingly when any of the inputs thereto is at a high level, representing a select condition, the NOR gate 51 will produce a low level output which now represents a select level; however, a high level output from NOR gate 51, which now represents the absence of a select condition, is only reproduced when all of the inputs thereto are low. The NOR gate 52 functions as an inverting AND gate, as aforesaid, and hence will only produce a high output level, which here represents a select or print condition, when all of the inputs thereto are low. However, when any of the inputs to NOR gate 52 are high, the output thereof will be low to thus indicate a no print or skip condition. As it will be recalled that a skip condition is indicated on skip conductors SKIP 1-3 by a high level while a no skip condition is indicated on skip conductors SKIP 1-3 by a low level and the NOR gate 51 will only provide a low level output on conductor 66 when at least one high or select input is applied thereto; it will be seen that all of the inputs of NOR gate 52 will be low to thereby produce a high level select signal when at least one select level is applied to NOR gate 51 and no skip level on conductors SKIP 1-3 is present. Under all other conditions, the output of the NOR gate 52 is low indicating a skip condition to thereby provide priority for skip signals which may be applied on conductors SKIP 1-3. The input to NOR gate 67 is a force high input which is employed when all the data cards scanned are to be printed and acts when the Print ALL

key (not shown) is depressed to force the output of NOR gate 52 high irrespective of any other inputs which may be applied thereto.

The output of NOR gate 52 is connected through conductor 68 to one input of AND gate 53 which may take the form of conventional AND gate means which produces a high output level only when both inputs thereto are high. The second or timing input to AND gate 53 is connected to the flip-flop 56 which, as aforesaid, produces a 1½ millisecond pulse at the termination of the timing pulse window. The output of the AND gate 53 is coupled through the inverter and buffer stage 69, which may take the same form as inverter and buffer stage 60, to the logic and control circuit illustrated in FIG. 4.

In considering the operation of the exemplary embodiment of the scanning and selection circuit illustrated in FIG. 3, it will be assumed that it is desired to print the document information from any data cards in a selected deck which have data combination 010 respectively in the three bit positions of the data cards present in the selected deck as well as document information from all data cards having a 1 in the first or third bit positions scanned except those having the combination 111, wherein mark information is taken as representing 1, no mark information is taken as representing a 0 and data channels A-C may be considered to be the first, second and third bit locations scanned, respectively. Under the exemplary select conditions specified the three position switch means S_{1A} and S_{1C} and AND selection module 1 may each be set to their no mark positions while S_{1B} is set to its mark position and the mode selection switch S_{M1} is set to the SELECT position to thereby provide for the printing of data cards wherein the data combination 010 appears in the bit positions scanned. Similarly the three position switch means S_{3A} and S_{3C} present in OR selection module 3 would be set to their mark position while three position switch means S_{3B} is set to its OFF or don't care position and the mode selection switch S_{M3} is set to its select position to thereby provide select levels from all data cards scanned having a 1 in the first or third bit position scanned. The exemption, i.e., don't print 111, for the general OR condition specified is provided by setting each of the three position switch means S_{2A} - S_{2C} in the AND selection module 2 to its mark position while setting the mode selection switch S_{M2} to its skip position to thereby provide for a no print level in response to the detection of the exempted condition. Thereafter the selected deck of data cards may be loaded in the feeder tray and the start button for initiating a selective printing operation depressed.

In the operation of the exemplary embodiment of the scanning and selection circuit illustrated in FIG. 3, as each data card is fed into scanning station B, its leading edge is detected by the card edge detector 50, as aforesaid, and after a sufficient delay has elapsed for the data on the fed data card to reach a position beneath the scanning means 50A - 50C, the scanning window timing generator means 54 will apply a pulse of sufficient duration to the flip-flop 59 in each data channel A-C to open the scanning window and maintain it in an open condition until the bit position data has been scanned and processed. Typical values for the delay provided between the detection of the leading edge of

the data card and the generation of the scanning window timing pulse may be of the order of 120 milliseconds while the duration of the scanning window timing pulse applied to conductor 55 may have an exemplary value of 25 milliseconds. When the scanning window is opened by the application of the timing pulse on conductor 55 to the preset input of flip-flop 59 in each of the data channels A-C, as aforesaid, the flip-flops 59 will be released from their forced reset condition so that their logic state may be set. At this instant, the detected data card will be at the scanning station and hence the output condition of scanning means 50A-50C will represent the mark or no mark condition of the selected bit locations on the data card being scanned. After threshold discrimination and inversion by the threshold amplifier means 57 and the inverter means 58, the output condition of each of the scanning means 50A-50C is applied as a setting input to the flip-flops 59 in such manner that a negatively directed pulse, indicating mark information, acts to set each flip-flop 59 to its high level while the absence of such a pulse maintains the flip-flop 59 in its reset or low output condition. The output level of the flip-flops 59 in each of the data channels A-C is inverted and buffered by the inverter and buffer stage 60 and applied to all of the selection modules 1-3. Thus, each of the flip-flops 59, due to the scanning window timing pulses applied thereto, acts as a properly timed gating device while allows data to be inserted therein only when the scanning of bit information is assured while allowing the possible skew of such bit information within reasonable limits.

The output of the data channel A is directly applied to the mark contacts of the three position switch means S_{1A} - S_{3A} and is additionally inverted at the inverter 63A and applied to the NO-MARK contacts of switches S_{1A} - S_{3A} . Similarly, the output level of data channels B and C are applied to corresponding contacts of three position switch means S_{1B} - S_{3B} and S_{1C} - S_{3C} , respectively in the same manner specified for the three position switch means S_{1A} - S_{3A} . The operation of the selection modules 1-3 and the decoder formed by NOR gates 51 and 52 will be explained in terms of the data conditions sought to be detected as set out above; however, it should be appreciated at the outset that as each data card is scanned under the control of the timing supplied by the scanning window timing generator means 54, the bit location information obtained will be compared with the conditions set in the selection modules 1-3 and thereafter decoded by NOR gates 51 and 52 so that either a select, a high level print signal, or a skip, a low level no print signal, is present at the output of the NOR gate 52 for each data card scanned. These select and skip signals at the output of NOR gate 52, which appear one at a time in sequence, are applied to AND gate 53 through conductor 68 and gated therethrough due to the action of flip-flop 56, as aforesaid, so that for each card scanned either a print or skip signal is applied to the print control circuit shown in FIG. 4 in a properly timed sequence representing the actual rate at which data cards are scanned at the scanning station B.

Under the exemplary conditions set forth above, whenever a data card having the data combination 010 is scanned, a high-low-high output level will be present at the outputs of data channels A-C, respectively, due to the inversion carried out by the buffer and inverter

stages 60. As the three position switch means S_{1A} - S_{1C} in AND selection module 1 are set to their NO-MARK, MARK and NO-MARK conditions, respectively, all of the inputs to NOR gate 61 on conductors 64A-64C will be low, due to the action of inverters 63A and 63C, satisfying the AND condition input requirements of this gate. Therefore, as the mode selection switch S_{M1} is in its select condition, a high level output will be present on conductor SELECT 1 while a low level output will be present on conductor SKIP 1. In AND selection module 2, it will be recalled that all of the three position switch means S_{2A} - S_{2C} are set to their mark condition for detecting a 111 condition and hence a high-low-high input condition will be applied to the inputs of the NOR gate 61 present in the AND selection module 2. Therefore, as the AND requirements of NOR gate 61 present in the AND selection module 2 are not met, both the outputs on conductors SELECT 2 and SKIP 2 will be low. Similarly in the OR selection module 2, three position switch means S_{2A} and S_{2C} are set to their mark condition while switch means S_{2B} is set to its OFF or don't care position which in the case of the OR selection module 2 is a high level, as aforesaid, to prevent the NAND gate 61 from producing a high level due solely to the setting of this position. Therefore, as none of the OR requirements of NAND gate 61 present in the OR selection module 3 are met, as only high level inputs are applied thereto, both the outputs on conductors SELECT 3 and SKIP 3 are low. Thus, when a 010 condition is scanned under the switch selection settings set forth above, conductor SELECT 1 has a high level thereon while conductors SELECT 2 and 3 and SKIP 1-3 are maintained at low level. NOR gate 51, as aforesaid, acts as an inverting OR gate and hence will produce a low output on conductor 66. Therefore, as a low level is present on conductor 66 as well as on all of the skip conductors SKIP 1-3, the AND conditions of NOR gate 52 are satisfied whereby the output of NOR gate 52 goes high producing a print signal for the selected condition which has been detected.

In a similar manner, whenever a data card having a 1 or a mark in the first and/or third position scanned bit location is detected, one of the following set of output conditions will be present at the outputs of data channels A-C due to the inversion carried out by the buffer and inverter stages 60:

	A	B	C
1	high	high	low
2	high	low	low
3	low	high	high
4	low	high	low
5	low	low	high
6	low	low	low

For any of these conditions, the output from AND selection module 1 will be on both the conductors SELECT 1 and SKIP 1 because the mode selection switch S_{M1} is set to SELECT thereby grounding conductor SKIP 1 while the 010 NO MARK-MARK-NO MARK setting of the three position switch means S_{1A} - S_{1C} will not satisfy the AND input condition required by NOR gate 61 for any data combinations set forth in the table. Similarly, for any of the input conditions listed in

the table, except the last, the output from AND selection module 2 will be low on both the conductors SELECT 2 and SKIP 2 because the mode selection switch S_{M2} is set to skip thereby grounding conductor SELECT 2 while the 111 or MARK-MARK-MARK setting of the three positive switch means $S_{2A} - S_{2C}$ will only satisfy the AND input condition required by the NOR gate 61 in response to a detection of the last data condition listed in the table. Thus, for data combinations 1-5 listed in the table, conductors SELECT 2 and SKIP 2 will both reside at a low level while in response to the last data combination listed in the table conductor SELECT 2 will be low and conductor SKIP 2 will go high.

The three position switch means $S_{3A} - S_{3C}$ in the OR selection module 3 are set, as aforesaid, to MARK-OFF-MARK so that any low level received at the mark input of the three position switch means S_{3A} or S_{3C} will meet the OR condition of NAND gate 61 therein and results in the production of a high level at the output thereof. Therefore, as the mode selection switch S_{M3} is in the select condition, receipt of any of the input conditions listed in the table will result in a high level on conductor SELECT 3 and a low level on conductor SKIP 3 as this conductor is grounded. Accordingly, it will be seen that for any of input conditions 1-5 listed in the table, conductor SELECT 3 will be high while conductors SELECT 1 and 2 and SKIP 1-3 are low. This meets the OR conditions of NOR gate 51 which places a low level on conductor 66 so that all low inputs are applied to NOR gate 52 resulting in the production of a high select level at the output thereof. When, however, input condition 6 as listed in the table is detected, a high is present both on conductors SKIP 2 and SELECT 3 while low levels are present on all of the remaining conductors. The high level on conductor SELECT 3, meets the OR requirements of NOR gate 51 so that a low is again present on conductor 66. The high on conductor SKIP 2, however, violates the and condition required by NOR gate 52 so that a low level output is present on conductor 68 and selectively gated through AND gate 53. Thus it is seen that the exemplary conditions for printing set forth above, are satisfied by the described settings for the selection modules 1-3 and result in select or print signals being gated to the logic and control circuit of FIG. 4 when the desired conditions are detected while skip signals are conveyed in response to the scanning of data cards not satisfying such conditions.

Logic and Control Circuit

FIG. 4 schematically illustrates an exemplary embodiment of a logic and control circuit for the selective printing apparatus according to the teachings of the instant invention. In the description of the exemplary logic and control circuit illustrated in FIG. 4, it may be assumed that conventional TTL circuitry is utilized throughout unless otherwise specified. The exemplary logic and control circuit illustrated in FIG. 4 comprises system clock 70, start-stop signal generator means 71, OR gate 72, flip-flop buffer stage 73, shift register means 74, logic control means for the developer motor 75, logic control means for the single revolution clutch 76, logic control means 77 for the selective transfer release 101, and counter means 78 for controlling the

operation of the relay for the start-stop signal generator 104. The system clock 70 may take the form of a radiation actuated clocking device which provides a pulse of a selected duration at a time corresponding to the feeding of a data card toward the scanning and exposure stations from the feeder tray. Although the function of the system clock may be implemented in several ways, it has here been accomplished by deriving a photosensitive input from the timing discs 3 and 4 mounted for rotation on the drive shaft 5 of the feeder roller 6 shown in FIG. 1. Thus, as shown in FIG. 1, a light source 7 is mounted on one side of the timing discs 3 and 4 and a photosensitive device 8 such as a phototransistor, photodiode or the like is mounted on the other side of such timing discs 3 and 4. Therefore, for each revolution of the feeder roller 6 the photosensitive device 8 shown in FIG. 1 will receive a radiation input when the trailing edge of disc 4 rotates past the photosensitive device 8 and such radiation input will be maintained until the leading edge of the disc 3 again blocks the input radiation from the light source 7. Accordingly, the photosensitive device 8 will, in the well known manner, generate a negatively directed pulse for each revolution of the feeder roller 6, whether a data card is fed or not, which pulse has a duration determined by the displacement θ between the trailing edge of the second timing disc 4 and the leading edge of the first timing disc 3. Conversely, the output of the photosensitive device 8 will be high during the entire interval ($360^\circ - \theta$) that it is blocked by the leading edge of the first timing disc 3 until it is again unblocked by the trailing edge of second timing disc 4 and it is this interval ($360^\circ - \theta$) which is employed to determine the duration of the clock pulses produced by the system clock 70. Thus, dark edge triggering is employed to drive the system clock 70 from the photosensitive device 8 and the time occurrence of the leading edge of the clock pulse produced thereby is determined by the position of the leading edge of the first timing disc 3 on the shaft 5 while the duration of the clock pulse as determined by the time occurrence of trailing edge of such clock pulse is determined by the position of the trailing edge of timing disc 4. Therefore, if it is assumed that in the data card embodiment of this invention being described, approximately three cards are fed per second, the feeder roller 6 may be treated as completing one revolution every 332 milliseconds to cause the photosensitive device 8 to produce one pulse for each revolution thereby defining a machine cycle time of 332 milliseconds. The system clock 70 may then take the form of a Schmitt trigger, flip-flop or other well known form of squaring circuit, arranged in the well-known manner to follow the output of the photosensitive device 8 applied thereto and hence to be triggered by the positively directed leading edge of the pulse produced by such photosensitive device 8 and reset by the negatively directed trailing edge thereof. For a machine cycle time of 332 milliseconds a clock pulse of approximately 230 milliseconds duration is appropriate and hence the displacement θ between timing discs 3 and 4 may be considered to be appropriate to set and reset the system clock 70 so that clock pulses having a duration of approximately 230 milliseconds are produced in response to the interval ($360^\circ - \theta$) of blockage. Furthermore, although the clock pulse dura-

tion is here adjustable by the adjustable positioning of timing discs 3 and 4, it will be appreciated that fixed duration timing pulses could be obtained by employing monostable multivibrators and under these conditions the number of timing discs could be reduced. Thus, under the conditions specified above for each revolution of the feeder roller 6, the system clock 70 will produce a clock pulse whose duration is approximately 230 milliseconds and whose leading edge is timed with the occurrence of the leading edge of the first timing disc 3 on the feeder roller 6. Although a Schmitt trigger or flip-flop has been indicated as forming the clock pulse generator for the system clock 70, it will be appreciated that other gating arrangements may be utilized therefor and that if extremely well defined or clean clocking pulses are desired a pair of Schmitt triggers may be employed to provide additional input definition. The output of the system clock 70 is connected through conductor 79 to a reset input for the flip-flop buffer stage 73, a clocking input for shift register means 74 and a timing input for the logic control means for the single revolution clutch 76 which controls the advancing of the transfer strip 9.

The start-stop signal generator means 71 comprises a relay which is actuated when the selective printing apparatus according to the instant invention is operating and deenergized to stop such selective printing apparatus. This relay is actuated by the depression of a start button for the apparatus and deenergized in a manner that will be rendered apparent below in conjunction with the description of the function of the counter means 78. Here, however, it is only important to note that whenever the relay in the start-stop signal generator is deenergized, a low logic level is present at the output thereof which acts to clear the shift register means 74 for the next operational run and inserts a low print signal into OR gate 72 so that a blank strip is printed in between selected printing runs of the apparatus according to the present invention. The output of the start-stop signal generator means 71 is connected through conductor 80 to a clear input of shift register means 74 and to one data input of OR gate 72.

The OR gate 72 comprises a conventional OR logic element which acts in the well-known manner to produce a predetermined output level whenever a selected input level is applied to either of the inputs thereto. One input of OR gate 72 is connected, as aforesaid, to the output of the start-stop signal generator means 71, while a second input thereof, as indicated, is connected to the output of the buffer and inverter stage 69 of the exemplary scanning and selection circuit shown in FIG. 3 and, accordingly, receives a sequence of gated select and/or skip levels therefrom corresponding to the print or no-print sequence of the deck of data cards being scanned. A low level input to the OR gate 72 represents a select or print instruction while a high logic level represents a skip or no-print instruction. It may be noted that for any given run, the first input to OR gate 72 is a low level from the start-stop signal generator 72 so that a blank strip print out initiates the print out sequence while the remaining inputs for the cycle are provided from inverter and buffer stage 69 in FIG. 3 and correspond to the print or no-print sequence associated with the deck of data cards being scanned. The output of the OR gate 72 is con-

nected to the input of flip-flop buffer stage 73. The flip-flop buffer stage 73 is a conventional flip-flop which is here employed to temporarily store each select or non-select signal applied to OR gate 72 for subsequent insertion into shift register means 74. The input to the flip-flop buffer stage 73 from OR gate 72 is connected to the Preset input thereof while the D input of the flip-flop is grounded, whereby a select or low input from OR gate 72 sets the flip-flop buffer stage 73 to a high state and the flip-flop is automatically reset to its low state on the application of a clock pulse thereto from the system clock 70. The output of the flip-flop 73 is connected to a data input of shift register means 74. The shift register means 74 may comprise a conventional 16 bit shift register used to clock select and skip levels through the system at the rate at which data cards are scanned and processed; however, as TTL logic is preferred, it will be appreciated that the 16 bit register is actually formed of two 8 bit register chips connected in series in a manner well known to those of ordinary skill in the art. In the shift register means 74, a high level as received from the flip-flop buffer stage 73 represents a select signal while a low level represents a skip. The shift register means 74 may be classified as a serial in, parallel out shifting configuration and only outputs 5-12 have been indicated in FIG. 4 as it is only these outputs which are here of interest. The clock input of the shift register means 74 is connected to the system clock 70, as aforesaid, while the clear input thereof is connected to the start-stop signal generator 71.

The relationship between the document information from a given card as it is processed according to the electrophotographic techniques employed by the present invention, as specified in conjunction with FIG. 1, and the scanned information from the data card resulting in a print or skip signal being shifted through shift register means 74 is such that when select or skip signal reaches output 5 of the shift register 74, the document information is being imaged on the photosensitive drum. The imaged information forming a latent electrostatic image enters the development station D at a point in time when its processed scanning information has been entered into the stage 6 of the shift register means 74 but has not yet propagated to stage 7. The image information is rotated through the development station D while scanning information from its data card is shifted through stages 7-9 and leaves the development station D about the time the scanning information from its data card has entered stage 10. When the scanning information reaches stage 12 of the shift register, the developed image has reached a point on the periphery of the drum, due to the rotation thereof, which is slightly ahead of the transfer station E. The presence of given bits of scanning information within certain stages of the shift register means 74 may thus be employed to control the selective operation of the developer motor 24, the single revolution clutch 15 and the selective transfer means 25.

Outputs 5-10 of the shift register means 74 are connected in parallel to the logic control means 75 for the developer motor 24. As was stated in conjunction with the description of FIG. 1, it is desirable to operate the developer 13 in a mode wherein it is normally off to conserve on the use of toner, etc. and thus to energize

the developer motor 24 just prior to the entry into the development station D of an image to be eventually transferred and to maintain it energized until an image to be transferred is no longer present within the development station D. This function is achieved by the logic control means 75 which comprises a pair of NOR gates 81 and 82 whose input conditions cause them to act as inverting OR gates in the same manner described with respect to NOR gate 51, as illustrated in FIG. 3. Outputs 5-7 of shift register means 74 are connected to the input of NOR gate 81 while outputs 8-10 thereof are similarly connected to NOR gate 82. The NOR gates will produce a low level output any time a high level input, representing select or print information, is applied thereto and hence an output will be produced from NOR gate 81 and/or NOR gate 82 at any time document information associated with a select signal is between the imaging station C and the development station D exit point. The outputs of NOR gates 81 and 82 are connected to the inputs of an OR gate 83 which may take the same form as OR gate 72 except the output thereof is capable of driving a winding 84 for energizing the developer motor 24. Accordingly, while the motor of the development station D is normally maintained in an off condition, the logic control means for the developer motor 75 functions to energize the development station D anytime a select signal is present in stage 5 of the shift register means 74 and maintains it in the energized condition so long as that or any other select signal is present within stages 5-10 of the shift register means 74. This allows the developer motor 24 to be maintained in a normally deenergized condition, but allows the energization thereof prior to the entry of an image into the development station D so that an appropriate level of toner flow is established prior to when the image to be developed enters the development station D and avoids intermittent operation of the development station D for succeeding select signals within a 6 bit range.

Outputs 11 and 12 of the shift register means 74 are connected to the logic control means for the single revolution clutch 76 which initiates a complete rotation of the paper advance pin wheel 16 in a single machine cycle i.e., 332 milliseconds, so that the paper is brought to the speed of the surface of the photosensitive drum 17 at or prior to its engagement therewith due to the actuation of the selective transfer means 25. The logic control means for the single revolution clutch 76 comprises first and second inverting AND gates 85 and 86 wherein the first inverting AND gate 85 controls the intermittent operation of the single revolution clutch while the second inverting AND gate 86 controls the continuous operation thereof. Each of the first and second inverting AND gates 85 and 86 may take the form of conventional logic gates which produce an inverted or low output level in response to a high level at each of the inputs thereto. A first input to the first inverting AND gate 85 is connected through conductor 79 to the system clock 70 while the second input thereto is connected through conductor 87 to the output of stage 12 of the shift register means 74. The first input to the second inverting AND gate 86 is connected through conductor 88 to the output of stage 12 of the shift register means 74 while the second input thereto is connected through conductor 89 to the output of stage

11. As it will be recalled that a bit in stage 12 of shift register means 74 is associated with document information just slightly in advance of the transfer point while stage 11 represents a bit associated with document information next preceding that in stage 12, it will be seen that the first inverting AND gate means 85 monitors whether or not strip advance is required for a present transfer while the second inverting AND gate means 86 monitors whether or not a transfer is to take place for the document information next to arrive near the transfer point. Further, it should be appreciated that as the duration of a pulse from the system clock 70, as aforesaid, is 230 milliseconds, while a machine cycle and hence the shifting rate of the shift register means 74 is 332 milliseconds, when a high level is present in stage 12 of the shift register means 74, the output of the first inverting AND gate 85 will go low only for the dwell time of the two inputs which is 230 milliseconds. Conversely, the second inverting AND gate 86 receives both inputs for a period equal to the machine cycle and hence if both stages 11 and 12 of shift register means 74 are high, the output of the second inverting AND gate 86 will stay low for a period of 332 milliseconds. Thus, as shall be seen below, when both stages 11 and 12 of shift register means 74 are high or contain select information, the output of the second inverting AND gate 86 serves to maintain the single revolution clutch for paper advance actuated until the stage 11 bit is shifted into stage 12 to thereby maintain continuous operation. The outputs of the first and second inverting AND gates 85 and 86 are connected to first and second inputs of an OR gate 90. The OR gate 90 may take the same form as OR gate 72 and acts to produce a low level output at any time a low level signal is impressed at one or both of the inputs thereto. The output of OR gate 90 is connected to one input of OR gate 91. The OR gate 91 may take the same form as OR gate 83 and acts to drive a winding 92 for actuating the single revolution clutch 15 which engages the paper advance pin wheel 16 for a single revolution bringing the transfer strip 9 up to the speed of photosensitive drum 17. A second input to OR gate 91 is provided by a strip feed signal generator means 93. The strip feed signal generator means 93 may take the form of a conventional button actuated signal generator which supplies a low level input to OR gate 91 whenever it is energized by the depression of the button by the operator. The purpose of the strip feed signal generator means 93 is to run the transfer strip 9 out of the machine after the last data card has been read and when no additional decks of data cards are to be inserted. As will be apparent to those of ordinary skill in the art, the OR gate 91 responds to a low level signal from the strip feed signal generator means 93 to drive winding 92 in the same manner as it responds to a low level input from OR gate 90.

The output of stage 12 of the shift register means 74 is also connected through conductor 94 to the logic control means for the selective transfer relay release 77 as is the output of the second inverting AND gate 86. The logic control means for the selective transfer relay release 77 comprises an inverting AND gate 95 and a flip-flop store 96. The inverting AND gate 95 may take the same form as the first or second inverting AND gates 85 and 86 and here functions to provide pulsed

operation for the selective transfer relay release 101. The flipflop store 96 may comprise a conventional TTL flip-flop which is here employed to provide continuous operation for the selective transfer relay release 101; it being noted that a flip-flop is here relied upon rather than an AND gate so that the storage capability thereof may be utilized to provide dwell for the shifting between stages 11 and 12 of shift register means 74 while timing problems are avoided. One input to the inverting AND gate 95 is connected through conductor 94 to the output of stage 12 of shift register means 74 while the second input thereto is connected through conductor 97 to selective transfer timing generator means 98. The selective transfer timing generator means 98 may be similar to the system clock 70 described above except that the clock pulses are of slightly longer duration and the triggering input for the timing pulse produced thereby is initiated by the pulse produced by the second photosensitive device 8' in response to dark edge detection from the second pair of timing discs 3' and 4'. Thus, when the second photosensitive device 8' is blocked by the rotation of the leading edge of the timing disc 3' of the second pair of timing discs 3' and 4' on the feeder roller shaft 5 past the light source 7, the second photosensitive device 8' will produce a positively directed triggering pulse for the selective transfer timing generator means 98. This triggering pulse will terminate upon the rotation of the trailing edge of the timing disc 4' past the light source 7. Thus, as this is a similar arrangement to that described with respect to the system clock 70, it will be seen that the selective transfer timing generator means 98 will produce a clock pulse having a duration equal to the interval $(360^\circ - \theta')$ defined by the displacement θ' between the timing discs 3' and 4' for each revolution of the feeder roller 6; however, the leading edge of the clock pulse produced by the selective transfer timing generator means 98 will be delayed with respect to the leading edges of clock pulses produced by the system clock 70 due to the adjustable displacement ϕ between the leading edges of timing discs 3 and 3', as shown in FIG. 2D. This allows the strip to come to speed prior to being engaged with the toner image on the photosensitive member 20. Thus while clock pulses from system clock 70 are initiated, as aforesaid, by the position of the leading edge of the timing disc 3, the selective transfer timing generator means 98 produces clock pulses which are initiated by the leading edge of the timing disc 3'. Therefore, the displacement ϕ between the leading edges of the timing discs 3 and 3' determines the time lag between pulses produced by the system clock 70 and the selective transfer timing generator means 98 and hence the time differential between when strip advance is initiated and the selective transfer relay 26 is released. This disc displacement ϕ is adjustable due to the adjustable positioning of timing discs 3 and 4, and 3' and 4', as aforesaid, but for the case of the printing of labels or the like would typically be such that a time lag of 10 milliseconds results.

The output of the second inverting AND gate 86 is connected to the data (D) input of flip-flop store 96 while the clock (C) input thereof is connected through conductor 97, to the selective transfer timing generator means 98. The flip-flop store 96, as will be obvious to those of ordinary skill in the art, may only be set by an

input from AND gate 86 upon the occurrence of a clock pulse from the selective transfer timing generator means 99 and will remain in this state until the next occurrence of a clock pulse when it may again be set to 5 the output state of AND gate 86. Therefore flip-flop store 96 may be set to its low state by a low input from the second inverting AND gate 86 whenever a clock pulse is produced by the selective transfer timing generator means 98 and remains in this state until it is 10 reset to its high state when AND gate 86 goes high and a clock pulse is produced by the selective transfer timing generator means 98. Thus, while the AND gate 95 responds to the presence of a select or high level in stage 12 of shift register means 74 to produce a low level output which occurs upon the receipt of the next clock pulse from the selective transfer timing generator means 98, the flip-flop store 96 is set to its low state 15 upon the occurrence of a clock pulse when select levels are present in stages 11 and 12 of shift register means 74, as detected by the second inverting AND gate 86, and remains in this state until the next clock pulse from the selective transfer timing generator means 98 allows to again follow the output of AND gate 86. This means 20 that while the output of inverting AND gate 95 will go low in response to a select level in stage 12 of shift register means 74 at the proper instant for the selective transfer timing generator means 98, and stays low only for the duration of such pulse; whenever a select level is 25 also present in stage 11 of shift register means 74, indicating that the next adjacent image is also to be transferred, flip-flop store 96 will be set to its low state and remain in this state at least until inverting AND gate 95 again goes low in response to the shifting of bit information from stage 11 to stage 12 and the occurrence of 30 the next clock pulse from the selective transfer timing generator means 98, to thereby insure continuous operation of the selective transfer means 25 upon the occurrence of adjacent selects. The outputs of the inverting AND gate 95 and the flip-flop store 96 are connected to an inverting OR gate 99. The inverting OR gate 99 may take the form of a conventional logic device which responds to the presence of a low level input at one or both of the inputs thereto to produce a high level output. The output of inverting OR gate 99 is 35 connected to the input of a driver stage 100. The driver stage 100 may take the form of a conventional TTL relay driving stage which responds to a high level input to produce an output signal of sufficient power to drive a relay. The output of driver stage 100 is connected to a 40 release winding 101 for the selective transfer relay 26 and acts when energized to release the selective transfer relay 26 so that the transfer strip is brought in rapid contact with the photosensitive drum, as aforesaid. Thus, after a suitable delay to allow the motion of the transfer strip 9 to come to speed, the logic control means for the selective transfer relay release 77 45 functions to release the selective transfer relay 26 and does so either in a pulsed or continuous mode depending upon whether or not the next succeeding image is to be transferred.

The counter means 78 may comprise a conventional 4 bit binary counter which acts in the well-known manner to count each of the inputs applied thereto

from its cleared state to an available count of 16. The clear input to counter means 78 is connected, as indicated, to the output of the scanning window timing generator means 54 through conductor 55 as indicated in FIG. 3. The data input of counter means 78 is connected through conductor 102 to the output of the system clock 70 so that the clock pulses produced thereby are counted. The function of the counter means 78 is to turn off the system by deenergizing the relay in the start-stop signal generator 71 described above, after all of the data cards loaded have been scanned and processed. As it will be recalled that scanning window timing generator means 54 produces a timing pulse only in response to the actual detection of the leading edge of a data card being fed, while the system clock 70 produces a clocking pulse for each revolution of the shaft of the feed roller 5; it will be appreciated that under normal operating conditions the counter means 78 will count a pulse from the system clock 70 and thereafter be immediately cleared by a pulse from the scanning window timing generator means 54. Thus, so long as data cards are being fed, the counter means 78 will normally register a count of one and then be immediately cleared unless, of course, the card feeding operation goes intermittent, in which case several counts might be registered. Once, however, the entire deck of data cards has been fed, no more clearing pulses from the scanning window timing generator means 54 will be present and hence the state of the count of the counter means 78, will be continuously incremented by clock pulses from the system clock 70. The output from counter means 78 is indicated in FIG. 4 as being taken from the fifteenth count position although any advanced stage could be used. The output of the counter means 78 is connected to driver stage 103 which may take the same form as driver stage 100. The output of the driver stage 103 is connected to the relay 104 for the start-stop signal generator 71 and acts when energized to release such relay and hence to deenergize the system as aforesaid. Thus, it will be seen that when the state of the counter means 78 reaches 15, indicating that no data cards have been fed in the last 15 machine cycles, the relay of the start-stop signal generator means 71 is released, shutting down the operation.

For the purposes of describing the operation of the exemplary logic and control circuit illustrated in FIG. 4, it will be assumed that a deck of eleven data cards is loaded and that the settings of the selection modules 1-3 in FIG. 3 results in the following sequence of information being applied to the input of OR gate 72 from the exemplary embodiment of the scanning and selection circuitry shown in FIG. 3:

Bit No.	Status
1	Select
2	Select
3	Skip
4	Select
5	Skip
6	Skip
7	Skip
8	Skip
9	Skip
10	Skip
11	Select

When the start-stop signal generator means 71 is operator actuated to initiate machine operation, a suitable delay to allow warm-up and relay closure occurs prior to the energizing of the relay in the start-stop signal generator 71 so that spurious data from noise does not present a problem. The relay in the start-stop signal generator means 71 in the deenergized condition acts, as aforesaid, to hold the shift register means 74 in a cleared condition and place a low level at the input of OR gate 72. Thereafter, this relay closes to initiate machine operation and the low level signal initially applied to OR gate 72 is loaded into flip-flop 73 as a first select bit which will hereinafter be referred to as the zero position bit. This select bit which has been automatically inserted at the beginning of the cycle provides a blank transfer strip at the output of the machine to identify a new cycle of operation.

The zero position bit is loaded into the first stage of the shift register means 74 from the flip-flop means 73 and is followed in sequence by bits 1-11, as set forth in the exemplary table, which are applied to the OR gate 72 from the scanning and selection circuit of FIG. 3 with each succeeding clock pulse, and thereafter applied to the flip-flop 73 for subsequent insertion into the shift register means 74. When the zero position bit reaches stage 5 of the shift register means 74, the high level setting thereof representing a select will be applied through conductor 105 to the input of NOR gate 81. This meets the OR requirements of NOR gate 81 which thereby produces a low level output which is applied through OR gate 83 to the developer motor winding 84 to thereby place the developer motor 14 in an energized condition. The document information, which here is blank, associated with the zero bit is now at the imaging station C. It should also be noted that at this time bits 1-4 as listed in the example have been loaded in stages 4-1 of the shift register means 74.

As the zero bit position propagates through shift register means 74 toward stage 10 thereof, the developer winding 84 will maintain the developer motor 14 in an energized condition due to the action of NOR gates 81 and 82 in response to the high or select value of the zero bit as well as their response to select bits 1,2 and 4 which are being clocked through the shift register means 74 over 332 milliseconds in sequence behind the zero position bit. Therefore, when the zero position bit reaches stage 10 of the shift register means 74, the output of NOR gate 82 is low due to the presence of the zero position bit in stage 10, the one position bit in stage 9 and the two position bit in stage 8 while NOR gate 81 is low due to the presence of four position bit in stage 6 of the shift register means 74. Thus, for the exemplary run set forth above, the normally off developer motor 24 will be energized upon the entrance of the zero position bit into stage 5 of shift register means 74 and will remain energized until the four position select bit reaches stage 11 of the shift register means 74. Thereafter, since bits 5-11 are skip signals or low levels which will not meet the OR requirements of NOR gates 81 and 82, the developer motor 24 will be deenergized and remain in this condition until bit 11 enters stage 5 of the shift register means 74. Accordingly, it will be seen that the developer is normally maintained in an off condition so that excess use of toner and residual toner build up is avoided but is energized at a sufficiently early point to assure an adequate toner flow in response

to the presence of an image to be transferred and is maintained in such energized condition so long as an image to be transferred is being formed on the photosensitive drum 20 or present within the development station D.

When zero bit position reaches stage 12 of shift register means 74, the high level associated therewith will be applied to inverting AND gates 85, 86 and 95 through conductors 87, 88 and 94, respectively, to prime these gates. At the same time that the zero bit is shifted into stage 12, the one position bit which is also a select is shifted into stage 11 and a clock pulse from system clock 70, which accomplishes such shifting is present on conductor 79. Therefore, the AND conditions of the first inverting AND gate 85 will be met and the output of this gate will go negative for 230 milliseconds which represents the dwell time between the machine cycle and the duration of the clock pulse. Similarly, the output of the second inverting AND gate 86 will go low due to the presence of a high or select level at each of the inputs thereto; however, the second inverting AND gate 86 will remain in a low condition for 332 milliseconds which represents the machine cycle time or the shifting rate of the shift register means 74. The outputs of the first and second inverting AND gates 85 and 86 thereby meet the OR conditions of OR gate 90 which produces a low output in response thereto. This low output is applied to the input of OR gate 91 which also goes low to thereby energize winding 92 of the single revolution clutch 15 to start the transfer strip 9 advance. The low output of the second inverting AND gate 86 is also applied to the D input of flip-flop 96; however, this flip-flop may not be set thereby until a clock pulse is produced by the selective transfer timing generator means 98.

After the transfer strip 9 has come to speed and at a time determined by the position of the leading edge of the timing disc 3' with respect to the leading edge of the timing disc 3, which may here be considered to represent a 10 millisecond interval, as aforesaid, the selective transfer timing generator means 98 will produce a clock pulse which, under the conditions listed above, enables inverting AND gate 95 and allows the flip-flop store 96 to be set by the input from the second inverting AND gate 86. However, although the output of the inverting AND gate 95 will only stay low for the duration of the clock pulse, the low output of flip-flop 96 remains low until it is subsequently reset by the change in output level of AND gate 86 and the coincident occurrence of a clock pulse from the selective timing generator means 98. Thus, both the output of the inverting AND gate 95 and the flip-flop store 96 go low and hence satisfy the input conditions of the inverting OR gate 99. The output of the inverting OR gate 99 thus goes high to thereby release the selective transfer relay 26 through the action of the relay driver 100 and the relay winding 101 to cause the transfer strip 9 to rapidly engage the photosensitive drum 20 in the manner described in conjunction with FIG. 1. Thus, it is seen that when a select level is present in stage 12 of the shift register means 74, the paper advance is energized and allowed to come to speed and thereafter the selective transfer relay 26 is released, thus deenergizing the selective transfer solenoid 27 so as to activate the selective transfer means 25 as described in

conjunction with FIG. 1 and to accomplish the selective toner image transfer.

When the one position select bit in stage 11 of the shift register means 74 is shifted into stage 12 and the two position select bit is shifted from stage 10 to stage 11, in the next machine cycle, the first inverting AND gate 85 will go low to be shortly followed by the inverting AND gate 95. However, due to the holding action of the second inverting AND gate 86 and the corresponding action of the flip-flop 96, the single revolution clutch 15 was never disengaged nor was the selective transfer relay 26 engaged. Thus, the transfer operation during this interval was continuous since the transfer strip 9 was continuously advanced and maintained in contact with the photosensitive drum by the selective transfer mechanism 25. Furthermore, as the two position bit in stage 11 is also a select, the holding action of the second inverting AND gate 86 and the flip-flop store 96, as explained above, will be repeated during this cycle of operation. When, however, in the next machine cycle, the two position select bit is shifted to stage 12, the three position skip bit is shifted into stage 11 of the shift register means 74. Thus, although the inverting AND gates 85 and 95 will be enabled by the select bit in stage 12 of the shift register means 74 to thereby continue to hold the single revolution clutch 15 engaged and the selective transfer relay 26 disengaged, respectively, for the duration of their respective clock pulses; the holding action of the second inverting AND gate 86 and the flip-flop store 96 will not be brought into play. Therefore, upon the termination of the system clock applied to the first inverting AND gate 85, the single revolution clutch 15 will be disengaged after a complete rotation to terminate the transfer strip advance. Similarly upon the termination of the clock pulse from the selective transfer generator means 98, the selective transfer relay 26 will be engaged to rapidly remove the transfer strip 9 from contact with the photosensitive drum 20 by the energization of the solenoid 27 and the rotation of selective transfer mechanism 25. This condition will continue for the exemplary sequence of data inputs specified above until bit 11 is shifted into stage 12 of the shift register means 74. At this time, pulsed mode operation will again commence due solely to the enabling of inverting AND gates 85 and 95 in the manner most recently described. Thus, it is seen that whenever a select bit enters stage 12 of the shift register means 74, corresponding to the position of associated document information near the transfer point E, the single revolution clutch 15 is engaged to initiate the advance of the transfer strip 9 and shortly thereafter, the selective transfer relay 26 is released to rapidly bring the transfer strip 9 into engagement with the photosensitive drum 20 by means of the deenergization of contraction solenoid 27 resulting in expansion spring 28 impelling selective transfer mechanism 25 to its second condition. This action, being under the control of the system clock 70 and the selective transfer timing generator 98, occurs in less than a machine cycle unless the preceding stage of the shift register means 74 also contains a select whereupon continuous action for the entire machine cycle obtains.

If it is assumed that the feed roller 6 is operating properly, the counter means 78 will receive a clock

pulse from the system clock 70 for each revolution of the feeder roller 6 followed by a pulse from the scanning window timing generator means 54 as the leading edge of the data card is fed and detected. As the system clock 70 is connected to the data input of the counter means 78 while the scanning window timing generator means 54 is connected to the clear input thereof, the eleven data card bit sequence considered above will result in the counter means 78 being set to a one count and then cleared 11 times. However, once the cards are exhausted, i.e., after the eleventh card is fed, clear inputs from the scanning window timing generator means 54 will no longer be received. Thereafter, as each pulse from the system clock is received, the counter means 78 will be incremented until the state of the count reaches 15. When the state of the count reaches 15, a signal representing this count is applied to the driver stage 103 to thereby cause the start-stop relay 104 to be deenergized and turn off the equipment. Another deck of data cards may then be loaded for additional operational runs or the strip feed signal generator means 93 may be actuated by the operator to run the transfer strip 9 upon which selective printing has occurred out of the selective printing apparatus.

CONCLUSION

Although the instant invention has been disclosed in conjunction with a single, detailed exemplary embodiment thereof, it will be appreciated that the broad concepts for selective electrophotographic printing systems disclosed herein admit of a wide ambit of variation and hence many modifications and alterations in the specific techniques set forth herein are available and contemplated by the present invention. For instance, although this invention has been disclosed in connection with elective printing apparatus wherein relatively small dimension document information on coded records is imaged and selectively transferred to a web or strip, it will be appreciated that the teachings of the present invention are fully applicable to document information of any dimension and in any format so that all forms of record information maintained on any conventional or convenient record format may be selectively retrieved and printed in accordance with the inventive concepts disclosed herein. Similarly, the principles taught by this invention are fully applicable to toner images of any dimension and to any transfer process employing any convenient form of transfer member such as a sheet, web, strip or drum. In a like manner, any convenient winding and reeling or sheet feed apparatus may be substituted for the transfer web driving apparatus shown so long as such substituted apparatus is capable of selectively stopping and starting the transfer member employed and once it is started bringing it rapidly to speed. Furthermore, although the present invention has been disclosed in terms of the transfer of complete toner images, the concepts taught herein may be employed with equal facility for the transfer of selected portions of toner images from appropriately coded records or the rearrangement of the format thereof on a transfer member. In addition, while optically coded record members have been treated herein, it will be apparent to those of ordinary skill in the art that other coding and scanning techniques, such

as magnetic coding and scanning, could be similarly employed and that the instant invention is independent of the specific electrophotographic process employed in the formation of an image to be transferred.

Furthermore, although specific circuit configurations have been set forth for the scanning, selection and logic and control circuits described herein it will be appreciated that many modifications may be made therein without any deviation from the inventive concepts taught by the instant invention. For instance, variable tapped delay configurations may be substituted for the shifting configuration shown, and as the position of discrete bits of select and skip information within the shifting configuration corresponds to the position of associated document information in the electrophotographic process, as many control outputs as desired may be obtained therefrom. Additionally, although specific logic configurations have been illustrated and described, any conventional logical arrangements which are calculated to achieve the same purpose may be substituted for the specific configurations shown while specific logic components may be varied at will to meet the choice of design. Further, within the selection circuit, more or less selection channels may be employed to meet the requirements of a specific design and either more or less selectivity within a given selection channel is readily available.

While the invention has been described in connection with a single exemplary embodiment thereof, it will be understood that many modifications will be readily apparent to those of ordinary skill in the art; and that this application is intended to cover any adaptations or variations thereof. Therefore, it is manifestly intended that this invention be only limited by the claims and the equivalents thereof.

What is claimed is:

1. A electrophotographic printing system comprising
  - a. means for feeding a plurality of records having coded information thereon in succession;
  - b. scanning and selection means including code sensing means for detecting said coded informations, and print selection means for establishing various preconditions and generating first signals representative of selected ones of said records whose coded informations satisfy such preconditions and second signals for those records whose coded informations do not satisfy said preconditions, such first and second signals being in the time sequence of scan of said records, and said first or second signals comprising high level signals and the other of said signals comprising low or zero level signals;
  - c. photosensitive means adaptable for continuous rotation;
  - d. optical means disposed at a first station at a peripheral location in relation to said photosensitive means for projecting optical images of the successively fed records onto said photosensitive means to form successive images on the surface of said photosensitive means as it is rotated;
  - e. development means disposed at a second station at another peripheral location in relation to said photosensitive means adaptable upon activation to develop said images formed onto said photosensitive means;

- f. image transfer means disposed at a third station at a further peripheral location with respect to said photosensitive means, and having a first operative condition for maintaining a transfer strip, positioned between said transfer means and said photosensitive means, at a distance sufficient from the surface of said photosensitive means to prevent image transfer to said transfer strip, and a second operative condition for bringing said transfer strip into a transfer relationship with the surface of said photosensitive means at said third station;
  - g. strip drive means adaptable during periodic activation to move said transfer strip between said photosensitive means and said image transfer means; and
  - h. control means including propagation means having a plurality of output stages, and logic circuit means connected to various of said stages and responsive to the presence of said first and second signals in various of said stages to provide control operations to at least one of said second and third stations.
2. A system in accordance with claim 1 hereof wherein said image transfer means comprises an ion emissive charging means fixedly positioned in the vicinity of said third station.
3. A system in accordance with claim 2 hereof, wherein said charging means is continuously energized.
4. A system in accordance with claim 3 hereof wherein said charging means comprises corotron means.
5. A system in accordance with claim 1 hereof, wherein said image transfer means comprises a transfer mechanism including strip support means and bistable drive means having a normally contracted condition and assuming an expanded condition in response to said control means.
6. A system in accordance with claim 5 hereof, wherein said drive means has one end thereof attached to said strip support means and the other end thereof fixedly positioned so as to move said strip support means toward and away from said photosensitive means in accordance with the condition being assumed by said bistable drive means.
7. A system in accordance with claim 6 hereof, wherein said strip support means comprises
  - a. a support frame; and
  - b. roller means supported by a central portion of said frame and having an axis of rotation parallel to the axis of rotation of said photosensitive means, said roller means being positioned by said support frame during the contracted condition of said bistable drive means in the proximity of said photosensitive means between said second and third stations and, upon the initiation of the expanded condition of said bistable drive means, to move toward said photosensitive means also between said second and third stations.
8. A system in accordance with claim 7 hereof, wherein one end of said support frame is coupled to anchor means in a manner enabling movement about a fixed pivot axis parallel to the axis of rotation of said photosensitive means, said pivot axis being on the same side of said photosensitive means as is said roller means.

9. A system in accordance with claim 8 hereof, wherein said strip support means comprises stripper means fixedly attached to said support frame and extending parallel to the axis of rotation of said roller means but removed therefrom so as to be located on the opposite side of said third station, said stripper means thereby being displaced a greater distance than said roller means when said support frame is moved about said pivot axis upon a change in the condition of said bistable drive means in response to said control means; and upon a change in condition of said bistable drive means from its expanded condition to its contracted condition, said stripper means in conjunction with said roller means applying stripping forces to said transfer strip at two closely positioned locations on opposite sides of said third station so as to overcome forces of attraction between said transfer strip and said photosensitive means.
10. A system in accordance with claim 9 hereof, wherein said stripper means comprises a stripper bar positioned to engage said transfer strip on the surface thereof adjacent to said photosensitive means as said roller means and said stripper bar are simultaneously displaced in a direction away from said photosensitive means by said support frame upon a change in the condition of said bistable drive means from its expanded condition to its contracted condition.
11. A system in accordance with claim 1 hereof, wherein said strip drive means comprises
  - a. strip restraining means on the side of said photosensitive member opposite to that whereat said third station resides; and
  - b. strip pulling means also positioned on said opposite side of said photosensitive means, said restraining means and said pulling means being so positioned with respect to each other that said transfer strip may extend from the former to the latter by way of said image transfer means.
12. A system in accordance with claim 1 hereof, wherein said strip drive means is responsive to said control means to sequentially move said strip transfer member a predetermined longitudinal distance upon each occurrence of the presence of each of said first signals in a particular stage of said propagation means, and to continuously maintain said strip transfer member in a condition of high tension during all operational conditions.
13. A system in accordance with claim 1 hereof, wherein said control means is adapted to receive and sequentially transfer each of said first and second signals in timed sequence so as to provide a direct correlation between various stages of said propagation means and various image positions along peripheral locations of said photosensitive means.
14. A system in accordance with claim 13 hereof, wherein said propagation means comprises a serial in, parallel out configuration.
15. A system in accordance with claim 14 hereof, wherein said propagation means comprises a shift register means.
16. A system in accordance with claim 13 hereof, wherein said logic circuit means includes a first logic circuit connected to a first plurality of stages of said propagation means corresponding to a first plurality of image positions about the periphery of said photosensi-

tive means that come between said first station and the exit of said second station, said first logic circuit being adapted to activate said development means only so long as there is an occurrence of at least one of said first signals in at least one of said first plurality of stages.

17. A system in accordance with claim 13 whereof, wherein said control means comprises a second hereof, circuit connected to a transfer stage of said propagation means associated with an image position abut said periphery of said photosensitive means slightly in advance of said third station, and also connected to a stage of said propagation means immediately preceding said transfer stage, said second logic circuit being adapted to activate said strip drive means upon the occurrence of one of said first signals in said transfer stage for a present image transfer, and to maintain said strip drive means activated if there is also an occurrence of one of said first signals in said preceding stage.

18. A system in accordance with claim 17 hereof, wherein said control means comprises a third logic circuit connected to said transfer stage of said propagation means and to said second logic circuit, said third logic circuit means being adapted to impel said image transfer means from said first operative condition to said second operative condition upon said strip drive means bringing said transfer strip up to the speed of the surface of said photosensitive means, and to maintain said image transfer means in its second operative condition if there is also an occurrence of one of said first signals in said preceding stage.

19. A system in accordance with claim 18 hereof, wherein said sensing means comprises a plurality of sensing devices positioned with respect to each other so as to simultaneously sense coded informations on a plurality of bit locations of each of said records scanned, and said data channel means comprises a plurality of data channel each connected to one of said sensing devices.

20. A system in accordance with claim 1 hereof, wherein said scanning and selection means comprises data channel means responsive to said sensing means in

the time sequence to provide high and low level signals in accordance with said detected coded informations, and selection means connected to said data channel means and having a plurality of alternative circuit conditions for establishing said preconditions.

21. A system in accordance with claim 20 hereof, wherein said selection means comprises a plurality of logic selection modules having their inputs connected in cascade to said data channel means, each of said plurality of logic selection modules having a plurality of alternative circuit conditions for establishing module preconditions therein, and logic decoder means connected to the outputs of said plurality of logic selection modules and adapted to sequentially generate signals in accordance with whether the coded informations of each of said scanned records satisfy any of said module preconditions and of said plurality of logic selection modules.

22. A system in accordance with claim 20 hereof, wherein said sensing means comprises a plurality of sensing devices aligned perpendicularly to the direction of record travel, said data channel means comprises a plurality of data channels each of which has its input connected to one of said sensing devices, and said plurality of logic selection modules having their inputs connected in cascade to outputs of each of said plurality of data channels.

23. A system in accordance with claim 1 hereof, wherein said strip drive means comprises

- a. strip restraining means positioned at a location along the path of longitudinal travel of said transfer strip preceding said image transfer means; and
- b. strip pulling means positioned at a location along the path of longitudinal travel of said transfer strip beyond said image transfer means, said restraining means and said pulling means being so positioned with respect to each other and to said image transfer means that said transfer strip is extended from the restraining means to the pulling means by way of, and in continuous engagement with, said image transfer means.

UNITED STATES PATENT OFFICE
CERTIFICATE OF CORRECTION

Patent No. 3700324 Dated October 24, 1972

Inventor(s) MARK A. HUTTER ET AL.

It is certified that error appears in the above-identified patent and that said Letters Patent are hereby corrected as shown below:

In the Drawings, Sheet 2, Fig. 3

Reference numerals "Select 1" and "Skip 1" extending from the block identified as "AND Selection Module 2" to NOR gates 51 and 52 should be identified as -- Select 2 -- and -- Skip 2 --, respectively.

Reference numerals "Select 1" and "Skip 1" extending from the block identified as "OR Selection Module 3" to NOR gates 51 and 52 should be identified as -- Select 3 -- and -- Skip 3 --, respectively.

Signed and sealed this 24th day of April 1973.
